UNITED STATES PATENT OFFICE.

ARTHUR F. POOLE, OF KENILWORTH, ILLINOIS, ASSIGNOR, BY MESNE ASSIGNMENTS, TO REMINGTON ACCOUNTING MACHINE CORPORATION, OF NEW YORK, N. Y., A CORPORATION OF NEW YORK.

CALCULATING MACHINE.

Application filed December 10, 1917. Serial No. 208,452.

To all whom it may concern:

Be it known that I, ARTHUR F. POOLE, a citizen of the United States, and resident of Kenilworth, in the county of Cook and State 5 of Illinois, have invented certain new and useful Improvements in Calculating Machines, of which the following is a specification.

My invention is an improved calculating 10 machine, designed particularly to handle the problem of writing customer's statements and individual ledger accounts for banks. There are many other uses to which my invention may be put and many forms of 15 counts which can be handled to advantage on it. But my invention is designed with the particular problem mentioned in view, and in the course of the following description of my invention I shall confine myself 20 solely to its use in the bank problem, although it is to be understood that there is a large number of other forms of accounts to calculate which my hereinafter described machine can be used with equal advantage.

25 The bank problem referred to is usually written according to the following form:

A	A'	B	C	D
Checks.	Total checks.	Deposits.	Prior balance.	Current balance.

30 and the arithmetical calculations on the numbers involved are

$$-A+B+C=D.$$

Occasionally an additional column A' is 35 used to write the total checks entered in any day. In this event numbers written in column A' are not included in the calculation but are simply copied from the totalizer.

My invention may be described generally 40 as a typewriter adding machine having a single jumping totalizer into which numbers are inserted seriatim by a master wheel and which is adapted to be brought into cooperation with numbers written on any 45 zone of the worksheet and therefore can be used to compute numbers which are written in horizontal arrangement. The totalizer is further an algebraic one, that is, it will show the correct resultant of a series of positive 50 and negative numbers.

The direction in which numbers set up on the keys are entered into the totalizer is controlled automatically by a set of cams trav-

eling with the typewriter carriage, there being a separate cam for each zone of calculation or column of numbers. One may set up a definite program of calculation as the typewriter carriage moves across the various calculating zones and the connections between the keys and the totalizer will be 55 automatically changed during the progress of the carriage, to the end that numbers written in some columns will be entered into the totalizer in addition, numbers written in other columns will be entered into the totalizer in subtraction and numbers written in other columns will not be entered into the totalizer at all.

In addition to the above described automatic control, my herein described machine 70 is also provided with a manual control and a means to shift from one to the other. It is sometimes desirable when a given program of calculation has been set up on the carriage to use the machine temporarily to calculate a form different from that determined by the automatic set up. For the handling of such cases I have provided a means to throw the machine into manual control and when in manual control to determine that 75 the totalizer shall operate either in addition or subtraction.

My invention further includes the provision of novel means for reversing the connection between the numeral keys and the 80 totalizers for the purpose of correcting an erroneous insertion. When a wrong number is inserted in the machine, for instance, a "527" is printed instead of the correct number "827", the usual procedure to correct the 85 error is to reverse the connection between the keys and the totalizer, reinsert the erroneous number, thus cancelling the previous insertion; the printing on the worksheet is then erased, the machine is put in 90 its original condition and the correct number inserted. As explained above, the control of my hereinafter described machine may be either manual or automatic, and either control may be in any one of three 95 conditions, viz., addition, subtraction or disconnect. The determination of the proper levers to operate in order to throw the machine into the reverse of any one of these six conditions would be somewhat complicated and I have therefore provided a single 100

universal reversing lever which when placed in its alternative position will reverse the previously-existing connections between the keys of the machine and the totalizer.

5 While this feature of my invention is covered broadly in a patent of mine, yet the application of it to my present machine is novel.

The cams forming the automatic set-up 10 are mounted on a bar which floats in reference to the carriage of the typewriter. This is for the purpose of insuring that the cams shall at all times be accurately spaced vertically in reference to the gear shifts while 15 at the same time allowing the utmost freedom of motion of the typewriter carriage. The cams themselves are also of improved structure, in that they are readily adjustable to determine that the totalizer shall operate 20 in addition, disconnect or subtraction and the cams themselves are mounted on a frame which is supported by the floating bar and can be readily adjusted lengthwise thereof. The same structure which supports the cams 25 also provides pickup lugs for the jumping totalizer and I have greatly improved this pickup mechanism in several particulars, which will be hereinafter fully set forth.

The algebraic totalizer herein employed 30 is quite an advance over those described in the prior art in that the insertion of the "one" necessary to show the correct resultant is performed, not by auxiliary mechanism as has been the case heretofore, but is inserted 35 through the medium of the master wheel and the keys of the calculating machine. The totalizer is so arranged that in case it changes from a positive to a negative resultant, or vice versa, no number is visible. 40 In order to make a number visible, it is necessary to operate a special key, located on the keyboard, and the operation of this special key adds a unit into the lowest place of the totalizer by means of the master 45 wheel and also shifts certain shutters or masks which have been concealing the exhibiting number. The correct resultant, both as to magnitude and algebraic sign is then displayed.

50 My herein described invention further includes the provision of automatically exhibited legends connected with the algebraic totalizer, which inform the operator both of the character of the indicated number, that 55 is whether said number is a positive or negative total, and also, at other times, inform the operator of the necessity to make certain operations at various stages in the calculation.

60 My herein described invention contains additional improvements in the mechanism of said special key as it is related to the ordinary numeral keys of the typewriter. Said improvements include an interlock for 65 said special key, to the end that it can not

be operated, except when the totalizer is in the proper position, at which time the ordinary numeral keys of the typewriter are locked.

In handling the bank system form, the 70 number in column D (supra) may be an overdraft, in which event the overdraft would be shown on the algebraic totalizer as a negative quantity. Under these circumstances, in order to clear the machine, it is 75 necessary to throw the universal reverse lever previously referred to and clear the machine by operating in addition. It is, of course, desirable to have some indication on the worksheet that an overdraft is present, both for the purpose of calling the attention of the bank officials to the matter and also for the purpose of information of the machine operator who handles this statement the next day. In picking up the previous 80 day's balance, when said balance was an overdraft it is of course necessary to enter this overdraft in the totalizer in a subtracting direction and it is very desirable to have both these overdrafts when they 85 occur either in the current balance column (column D supra) or in the prior balance column (C supra) strikingly visible, so that the operator may be clearly guided in entering these overdrafts into the totalizer in the 90 proper direction.

From the above it is apparent that whenever an overdraft is handled, either by way of clearing it from a totalizer or entering it into the totalizer as is done when the prior 100 day's balance is picked up, it is necessary to operate the universal reverse lever. In order to make the printing of these overdrafts characteristic, I have connected the universal reverse lever with the color shift of the typewriter, so that operating the universal reverse lever simultaneously shifts the ribbon from its customary color, for instance black, to its distinctive color, for instance red. I believe that this combination of an algebraic 110 totalizer and universal correcting lever for the same and a connection from said universal correcting lever to a color shift is broadly new and I consider it a very essential portion of my invention.

115 My herein described machine is a further improvement over those of the prior art in that I have provided a species of carriage lock for a jumping totalizer machine. This carriage lock is operative on the main writing carriage of the typewriter and prevents the shifting of the same while a numeral key is depressed. I believe I am the first to show a single jumping totalizer machine equipped with the above described lock.

120 My herein described invention further discloses an improved pick-up and release mechanism for the jumping totalizer which is designed to prevent the jumping totalizer from running ahead of the main carriage and acts 130

to maintain said totalizer in exact correspondence with the main carriage while said main carriage is traversing a calculating zone. The jumping totalizer is provided 5 with an adjustable stop which determines the normal position of said totalizer and this stop is connected to the pick-up and release mechanism so that there is no interference with the main carriage of the typewriter which is accordingly free to be moved 10 in its reverse or backspace direction when the totalizer is resting against its backstop.

Another object of my invention is the provision of an adjustable stop to determine 15 the normal position of the jumping totalizer carriage, which stop will cooperate with the pick-up and release mechanism above referred to. This adjustable stop is so designed that it can be adjusted to any width 20 of totalizer and at the same time will automatically operate portions of the pick-up and release mechanism to correspond to this changed adjustment.

A further object of my invention is the provision of a special interlock between the 25 decimal carriage, the digit keys of the typewriter and the adjustable stop referred to above, to the end that if the decimal carriage becomes accidentally disconnected from the moving carriage of the typewriter before 30 a number has been completely written the calculating machine is locked. On the other hand, when said decimal carriage is disconnected from the main carriage and the calculating machine is not in a computing 35 zone, the digit keys of the typewriter may be operated as usual.

A further object of my invention is the provision of a certain restoring lever which 40 is designed to release the actuating mechanism in case it becomes accidentally locked by reason of an erroneous manipulation thereof. Owing to the complicated nature 45 of this machine, it is necessary that this restoring lever compel the parts to return to their normal position in a certain cycle in order to avoid introducing an additional error by the act of restoring the machine to its normal position. To this end I have 50 provided said lever with a series of interlocks so that when the said lever is used certain parts of the mechanism must return to their normal position in a cycle as determined by the lever and its associated mechanism.

Another object of my invention is the provision of an interlock between said lever and the digit keys of the typewriter, to the end 55 that it is impossible to operate any of the digit keys until the parts controlled by the restoring lever have been returned to their normal position.

A further object of my invention is the provision of certain novel cam and pick-up 60 supporting frames, these frames including

as a single structural unit certain cams to determine the direction in which numbers shall be entered into the totalizer upon actuation of the digit keys, certain other cams determining a species of interlock between 70 the digit keys, jumping totalizer and the frames themselves, and also the pick-up lug by means of which connection is made between the carriage of the typewriter and the jumping truck upon which is mounted 75 the totalizer. I have mounted these frames on the floating cam bar previously referred to and have provided said frames with attaching means, to the end that the frames may be readily adjustable to any desired 80 position on the cam bar and securely held in their adjusted position.

A further object of my invention is the provision of an improved latch structure serving to connect the typewriter carriage 85 and the subsidiary decimal carriage or truck on which the totalizer is mounted. The novel features of this latch structure will be more fully explained in the following specification: It may be said generally that its 90 function is to prevent accidental disengagement of the subsidiary decimal carriage from the typewriter carriage regardless of how the latter may be moved. This latch structure also includes novel means for preventing interference between the typewriter carriage and the subsidiary decimal carriage 95 when the latter is in its normal position.

A further object of my invention is the provision of certain structural details of the 100 actuator and mounting for the jumping decimal carriage, to the end of providing a structure which will be easy of assemblage and in which the parts will be rigidly held in their proper positions. These and other 105 structural details will be more fully pointed out and referred to in the following specification and claims.

My invention may be best understood by reference to the accompanying figures, of 110 which—

Fig. 1 is a front elevation of the complete device on a typewriter;

Fig. 2 is a side elevation of the complete device on a typewriter;

Fig. 21 is a detail of support 108 for lever 105, and

Fig. 22 is a section on the line 22—22 of Fig. 3.

Similar numerals of reference refer to like parts throughout all the figures.

The preferred form in which I have shown my invention is in connection with the well-known Wahl typewriter adding mechanism, in fact, I have used a great deal of the Wahl mechanism in carrying out my invention, although my invention is by no means limited to be used in the precise form disclosed by me in the following specification.

Reference to Figs. 1 and 2 disclose that my mechanism is mounted on a Remington typewriter 30 which is provided with the customary ten digit keys 31, each of which is connected by a pull rod 32 acting on a rocker 33, pivoted at 34 on the framework 29, and which is also connected by a pull rod 35 to a type bar 36 pivoted at 37 on the framework 27, and provided with the proper printing type 38 for printing on a platen 39. A universal rod 40 is suspended by a pair of links 41, (of which but one is shown in Fig. 2) from the arms 42 rigid on a shaft 44 pivoted to the framework 29. Rigid with the shaft 44 is an arm 43, from which leads a rod 45 to the escapement rocker 46, which is pivoted to the framework at 47 and engages the twin escape-wheels 48 of the usual Remington escapement.

It is to be understood that the typewriter is also provided with alphabetical printing keys. I have not shown any of these keys for the reason that they are not connected with the calculating mechanism and indeed in some cases, for example in handling the bank problem referred to above, the presence of alphabetical printing keys is superfluous. When these alphabetical keys are present, each of said keys actuates the universal escapement rod 40 in the same manner as the digit keys 31.

In addition to the digit keys 31, I have also provided a special key 50, which is connected by a pull rod 49 to the computing actuator. This special key 50 is not provided with a pull rod 32 and has no type bar connected therewith. Said key has to do with certain operations connected with the algebraic totalizer and the mechanism connecting said key to the totalizer will hereinafter be fully described.

My improved machine consists primarily of an actuator which is contained between two end side plates 279 and 280, which are mounted on a casting 281, which serves as the foundation support for the calculating mechanism. Said casting is attached by suitable means (not shown) to brackets on the typewriter 30. The casting 281 also furnishes a support for a certain reciprocating truck 221 (Fig. 3) which serves as the totalizer mounting and said casting also supports the intermediate side plates 282, 283, and 284, between which certain other portions of the actuator mechanism are pivoted. The actuator casting 281 further serves as a support for the cam bar 172 (Fig. 3), which is supported from a pair of rollers 178 and 179 (Fig. 2), all of which will be hereinafter more fully described.

Numbers are inserted into my improved machine by a set of digit keys 31, and the motion of these keys is transferred to a series of fans 52 by a series of pull rods 51. There is one of said fans attached to each of the pull rods 51, and also to the pull rod 49. All of the fans 52 are rotatably mounted on a shaft 53, which is fixed in the framework 279, 280, 281. Reciprocation of any of the digit keys results in a corresponding reciprocation of the attached fan 52, and eventually results in the differential rotation of a master wheel 54 (Figs. 1, 3, 7 and 9) which is rigidly mounted on a shaft 55, which rotates in the frame plates 282 and 284. On the first part of the downward motion of any of the digit keys 31, certain universal actions take place in the actuating mechanism, that is, actions which are the same both in time and extent for any of the digit keys 31. Among these actions are the action of a front full-stroke pawl 56, which is rotatably mounted in the framework of the machine and is held by a spring 57 extending between said pawl and the back full-stroke pawl 58 into the path of a series of teeth 59 cut on each of the fans 52. During said preliminary portion of the numeral key stroke the back full-stroke pawl 58, which is also rotatably mounted in the framework, is thrown out of the path of a set of teeth 60, which are present on each one of the fans 52. The

action of these full-stroke pawls has been thoroughly described in the issued patents to John C. Wahl, Nos. 893,719 of July 21, 1908 and 1,270,471 of June 25, 1918, reference to which may be had for further information on this subject.

The universal actions on the first part of the key cycle also include the counter-clockwise rocking of a certain master dog 61, (Fig. 9) which is mounted on a shaft 62 rotatably mounted in the framework and which, when actuated, serves to unlock the gear chain in the totalizer. The master dog 61 is actuated by means of a roller 63 attached thereto, which in its turn is actuated by a cam slot 64 in a rocker 65 on a shaft 66 rotatably mounted in the framework. The rocker 65 has mounted on it a stud 67 engaging with which is a link 68 which 10 serves to connect said stud with a rock-shaft 69 rotatably mounted in the framework. Mounted on the rockshaft 69, by arms 285, and rigid with said shaft is a rod or bail 70, which extends in the path 20 of the heels 71 of the fans 52. When a digit key 31 is depressed, the consequent rotation of the fan 52 will bring the heel 71 into contact with the bail 70. The rockshaft 69 will thereupon be 30 rotated in a clockwise direction (Fig. 9) and rotation of the rocker 65 will consequently take place. The cam slot 64 will then move the roller 63, thus maintaining the master dog 61 in its alternative position. These actions have been thoroughly described in the patent to Wahl, No. 1,148,733 of August 3, 1915, and therefore need not be described in greater detail here.

Each of the fans 52 is provided with a slot 72, which is adapted to engage a pin 73, mounted in a gooseneck 74, which is rotatably mounted on the shaft 53. There is a gooseneck 74 associated with each of the fans 52 and each of the goosenecks 74 has a cam surface 286 and a concentric slot 287 which are adapted to engage one of a series of rollers 75, which are supported by arms 76 from a sector shaft 77. The arms 76 are mounted on the shaft 77 in spiral arrangement and therefore the operation of any of the digit keys 31 will rotate the sector shaft 77 a differential amount. The rollers 75 are so arranged that when the 1-key is operated, the shaft 77 will be rotated one space; when the 2-key is operated said shaft will be operated two spaces, etc.

The differential rotation of the sector shaft 77 is transformed into a differential rotation of the master wheel 54 by the well-known Wahl helical cam and sector mechanism, for a description of which reference to the cited patent of Wahl, No. 1,148,733, will be of advantage. The result of this 65 mechanism is that a certain sector 78 (Fig.

3), which is pivotally mounted at 79 on the sector shaft 77 is moved by a shiftable plate 80 from the position shown in Fig. 3 to a position where said sector is at right angles to the sector shaft 77. This shifting of the 70 position of the sector relative to the shaft 77 is done by the rocking of the universal shaft 69 on the first part of the downstroke of any of the numeral keys. When the sector 78 is in its right-angled position just 75 described, it may be in mesh either with a direct gear 81 or a reverse gear 82 (Fig. 7) according to the position of said gears. The direct gear 81 has a tongue 83, which is in slidable engagement with a fork 84, 80 rigid to the master wheel 54. The reverse gear 82 is rotatably mounted on a gear shift rod 85 and is held from shifting laterally relatively thereto by washers 86 and 87 mounted on said rod. The rod 85 is slidably 85 mounted in the side plate 282, which is rigid to the framework and has a portion of reduced diameter 89 which slides in a hole in the side plate 283, also rigid to the framework. Mounted on the side plate 282 is a 90 stud 91, pivotally mounted in which at 92 is a lever 93 having a connection by means of a stud 94 to a cut 95 on the underside of the washer 86 (Fig. 7). The hub of the direct gear 81 has a slot 96 cut therein 95 and said slot is in engagement with a stud 97, mounted on the rocker 93. It will thus be evident that shifting of the gear shift rod 85 will result in the shifting of the direct gear 81 and the reverse gear 82 in opposite 100 directions. These gears have three possible positions. One is the position shown in Fig. 7, in which the reverse gear 82 is in a position to be engaged by the sector 78. This 105 position of the gears determines that the master wheel 54 shall rotate in a direction to determine subtraction in the totalizer. The second position of the gears 81 and 82 is a position in which the two gears are substantially in line and neither of them will 110 be engaged by the sector 78 when the same is actuated. This corresponds to a disconnect position of the machine and in this case any number entered by the digit keys will simply be printed on the worksheet without 115 being entered into the totalizer. The third position of the two gears is the position when the gear shift rod 85 is drawn to its extreme lefthand position (Fig. 7) and when in said 120 position the direct gear 81 will be engaged by the sector 78. This is the addition position of the machine.

From what has been said, it will be obvious that depression of any of the digit keys 31 will result in the master wheel 54 and the 125 master dog 61 operating in the following cycle: During the first part of the motion of the key the master dog 61 is rocked in a counter-clockwise direction, after which the master wheel 54 is rotated a differential 130

amount, whose extent is determined by the particular numeral key which has been operated and whose direction is determined by the position of the gear shift rod 85. I shall hereinafter describe the mechanism for determining the position of said gear shift rod.

After the numeral key has reached the bottom of its stroke, the universal bail 70 (Fig. 9) snaps off the heel of the fan 52, being thus moved by a sector spring (not shown) which serves to hold the rockshaft 69 in its normal position, as shown in Fig. 9. On the upstroke of the key, the snapper 78 is thrown out of mesh with the gear engaged by it during the downstroke of the key and the upstroke of the key is accomplished without any further motion of the master wheel 54. This action is also described in the Whal Patent 893,719 supra.

The gear shifts.—I have now described the mechanism by means of which the master wheel 54 is rotated an amount whose extent is determined by the particular numeral key depressed and whose direction is determined by the gear shift rod 85. It is obvious that when the master wheel 54 rotates in one direction it will determine addition in the totalizer and when it rotates in the opposite direction it will determine subtraction. Furthermore, I have provided an intermediate position for use in certain classes of calculation in which a depression of a digit key will not rotate the master wheel at all, but the number will simply be printed on the platen without being entered into the totalizer. My mechanism is so designed that this disconnect position corresponds to an intermediate position of the gear shift rod 85. In order to determine the position of this gear shift rod, I have provided three distinct mechanisms, any one of which, either by itself or acting in conjunction with one of the others, is sufficient to determine the position of the gear shift rod 85. The first of the various mechanisms just recited is an automatic control, which consists of a series of cams mounted on the cam bar 172 which travels step by step with the advance of the typewriter carriage. These cams contact with a pair of complementary rollers and under certain circumstances the position of said rollers determines the position of the gear shift rod 85.

A second way of controlling the position of the gear shift rod 85 is by means of an add and subtract handle 98 located at the lefthand side of the actuator and adapted to occupy any one of three positions. In its uppermost position (the position shown in Fig. 3) it determines that the gear shift rod shall be in the position shown in said figure, which position determines addition. In its intermediate position it does not act on the gear shift rod 85 at all but throws

said rod under the automatic control of the previously mentioned cams mounted on the cam bar 172. The mechanism by which said cams act on the gear shift rod 85 will hereinafter be fully described. The lower position of the handle 98 determines that the gear shift rod shall be in a position determining subtraction by the master wheel 54 whenever any of the digit keys 31 are depressed.

The third way of controlling the gear shift rod 85 is by means of the correcting handle 160, which and its connections will be described hereinafter.

I shall now proceed to describe the different mechanisms by which the gear shift rod 85 is located as above described. Considering the automatic mechanism first, reference particularly to Fig. 14, in which is shown a perspective view of the various gear controls, will disclose that the rod 85 is connected by a pin 99 to the lever 100, which is rigid on a shaft 101 rotatably mounted in the actuator casting 281 and extending through the same. On the rear end of said shaft is mounted a crank arm 102, rigid in which is a pin 103, which is adapted to be moved by a V-shaped slot 104 in a floating cam plate 105. The location of said plate is controlled by the joint action of two pivots, first that of a pin 106, which is constrained to move in a vertical slot 107 (Fig. 21) in a plate 108 supported on the back of the actuator casting 281. The pin 106 is riveted into a link 109, and said pin passes through a slot 110 in the floating cam plate 105, the slot 110 being parallel to the length of the cam plate 105. A pin 112 is riveted in the rear end of the floating cam plate 105 and is constrained to move in a vertical slot 111 in the plate 108 (Fig. 21), said plate being fastened to the actuator casting 281 by screws 113 and 114. The pin 112 may be acted on by either of two agencies, first by a plate 115, which contains a slot having a wide portion 116, a portion 117 which is just the width of the pin 112 and an end portion 118, which, like the portion 116, is wide enough to permit the pin 112 to be actuated by the second source of control for said pin. Leaving out of consideration for a moment this second control, reference to Fig. 14 will disclose that the plate 115 is pivoted at 119 to a bell crank 120, which is rotatably mounted on a stud 121 rigid on the framework. Mounted on the bell crank 120 is a stud 122, mounted on which is a roller 123, which is adapted to be actuated by the traveling cams hereinafter to be described. The depending arm of the bell crank 120 is connected by a link 124 to a depending arm 125 of a bell crank 126 pivoted to the framework on a stud 127 and having mounted on its horizontal arm a roller 128. The length

of the link 124 is such that when the roller 123 is lowered the roller 128 is raised the same amount and vice versa, so that the motions of the two rollers 123 and 128 are 5 complementary to each other. Obviously the motion of the rollers will determine the up and down position of the pivot 119 of the plate 115 and in the event that said plate is swung about the pivot 119 10 to such a position that the pin 112 will register with the narrow portion 117 of the slot in the plate 115 then the motion of the rollers 123 and 128 will completely control the position of the pin 112 and consequently 15 the position of the left end of the floating cam plate 105.

I shall now describe the means by which the pin 112 is controlled from the handle 98. On the opposite side of the floating cam plate 105 from the plate 115 is a second plate 129 which is pivoted to the framework on a stud 130. Said plate 129 has in it a slot 131 having a wide central portion 132 and narrow end portions 131 and 25 133. The position of the end portions 133 and 131 is such that when the pin 112 is engaged by them it is thrown into either of its alternative positions, that is, when engaged by the end 133 it is thrown into 30 position determining that said pin 112 shall be in its upper position (Fig. 14) and when the end 131 engages the pin 112 said pin is thrown into its lower position, the ends 116 and 118 in the plate 115 being wide 35 enough to permit such motion. The plate 129 is shifted from one position to another by means of a pin 134. The pin 134 is riveted to a link 135 and extends through a hole 137 in the plate 129. The pin 134 40 also engages a slot 136 in the plate 115, said slot being of sufficient length to permit the motion of the plate 115 as determined by the motion of the bell crank 120. The link 135 is pivoted on a stud 138, which is 45 mounted on a rocker 139, rotatably mounted on the framework on a stud 140. The rocker 139 contains a slot 141 engaging in which is a stud 142, mounted in the end of a lever 143, which is pivoted to the 50 framework on a stud 144 and is connected by a twisted link 145 to the rear end of the handle 98, which in its turn is pivoted to the framework on a stud 146. An escutcheon plate 147 is provided for the lever 98 and 55 has three recesses or locations therein, said lever being held by a spring (not shown) to engage any one of said locations, thereby preventing accidental shifting of said lever. When the lever 98 is in its middle 60 position, the plates 115 and 129 are in a position in which the pin 112 is in engagement with the narrow part 117 of the slot in plate 115 and opposite the wide portion 132 of the slot in the plate 129. When the 65 lever 98 is in either of its extreme positions,

the pin 112 will be located by either of the ends 133 or 131 of the slot in the plate 129 and the wide portions 116 or 118 of the slot in the plate 115 will permit the plate 115 to be moved up and down without interference with the pin 112. 70

Obviously the pin 112 may thus be located from either of two sources, first, from the complementary rollers 123 and 128 and second from the handle 98. When said 75 handle is in its middle position it determines that the pin 112 is controlled by the complementary rollers 128 and 123. When the handle is in either of its extreme positions it determines that the pin 112 is located 80 by the plate 129. The ends 133 and 131 of the slot in plate 129 are so arranged that the pin 112 is located in a position determining addition when the handle 98 is in its uppermost position (Fig. 3) and in a position determining subtraction when said handle 98 is in its lowermost position (Fig. 3). 85

When the parts are in the position in Fig. 14, the gear shift rod 85 is shown in its addition position. Obviously if the plate 129 should be shifted so that the end 131 of the slot therein controls the position of the pin 112, the floating cam plate 105 would be 90 rocked about the pivot 106 and the pin 103 would occupy the middle portion 148 of the slot 104. This would result in the rocking 95 of the shaft 101 and the consequent shifting of the gear shift rod 85 from its addition to its subtraction position.

I shall now describe the third way of controlling the odd and subtract function, which is by the action of the pin 106: As before noted, said pin is constrained to move in a vertical slot in the plate 108 (Fig. 21) and is riveted in the link 109, said link being pivoted on the end of a horizontal arm 149 of a bell crank 150, pivoted on the stud 140 previously referred to. The depending arm of said bell crank has riveted therein a pin 151, connected to which is a spring 152, the other end of which is connected to a stud 153 in a link 154, said link having a slot 155 therein which engages a forwardly extending portion of the pin 151, previously referred to. The link 154 has in its righthand 110 end (Fig. 14) a stud screw 156, which engages a slot 158 in a bell crank 157, said bell crank being mounted on the stud 144 previously referred to. The bell crank 157 is connected by a twisted link 159 to a universal correcting lever 160 (Figs. 3 and 4). Said lever is pivoted to the framework on a stud 161 and is held in its normal position by a spring 162. When said lever is thrown to its alternate position a latch 163 is provided to retain it in said position. The parts 162 and 163, just referred to, are the same parts as parts 362 and 364 in Fig. 5 of the patent to Wahl, No. 1,270,471. 115 120 125

The locations of the pins 106 and 112 and 130

the travel of the universal correcting lever 160 are so proportioned that motion of said lever and consequent motion of the pin 106 will displace the floating cam plate 105 an 5 angular distance about the pin 112 equal to half of the angle subtended by the extremities of the slot 104. Obviously displacement of the cam plate 105, by motion of the pin 106, will throw the pin 103 into a position 10 which is determined by the slot 104 moving through half of its angular length. Inspection of Fig. 14 will disclose that if the pin 103 is in the position shown in said figure, that is, in the addition position, displacement 15 of the pin 106 by the motion of the correcting lever 160 will bring the pin 103 into the portion 148 of the slot 104, that is, into its subtraction position. Therefore, the machine will be reversed.

20 If the pin 103 is half way up the slot 104, thus corresponding to a disconnect position, motion of the pin 106 will bring the pin 103 half way down the slot 104 on the other side of the hump 148, that is, it will bring the pin 25 103 into a second disconnect position. If the pin 133 occupies the portion 148 of the slot 104, motion of the pin 106 will bring the pin 103 into the lower portion 164 of the slot 104, that is, the pin 103 will be shifted 30 from the subtraction position to the addition position. Obviously the pin 106 may be moved irrespective of the position or state of control of the pin 112, and therefore the universal correcting lever 160 may be operated when the lever 98 and the rollers 123 and 128 are in any of their possible positions and when operated will throw the machine into the reverse of its previous condition.

35 40 I consider this universal correcting lever of great advantage. The most convenient way to correct an erroneous insertion in the adding machine is to throw the machine into the reverse of its previous condition, re-inserting the erroneous number, thereby cancelling the first insertion, then throwing the machine to its original position and inserting the correct number. Obviously when a machine may be either under manual or 45 50 automatic control, if one had to manipulate different levers to reverse the machine in order to correct the error, such manipulation would be very inconvenient and liable to error. In my herein described machine 55 I have provided a single correcting lever, which, when operated, will place the machine into the reverse of its previous condition. I consider this a feature of great importance. The principle of the device is 60 somewhat the same as the principle of a device for a similar purpose on a two-totalizer machine shown in one of my copending applications. However, the mechanism disclosed in my present specification to accomplish this result is much simpler than the

means disclosed in my cited application. This simplicity arises from the fact that in my present application the calculating machine has but one totalizer and therefore no reverse of a manual disconnect position is 70 required since the manual disconnect may be obtained by the usual disconnect lever 165 (Fig. 3) always present on the Wahl machine.

75

The automatic set-up.

I shall now describe the means for actuating the rollers 123 and 128. It will be recalled that one of the objects of my improved machine is the possibility of setting up a 80 definite program of calculation on the carriage, and having the motion of the carriage automatically determine the position of the gear shift rod 85 as the various zones of calculation are reached. As explained in the previous chapter, the automatic shifting of the rod 85 is done through the agency of the complementary rollers 123 and 128. It is obvious that the roller 128, the bell crank 126 and the connecting link 124 could be 85 suppressed and a returning spring attached to the bell crank 120 to perform the function of the roller 128. However, I prefer the complementary roller arrangement shown in Fig. 14 for the reason that in case 90 one has a returning spring, the spring must be strong enough not only to shift the mechanism when the return of the roller 123 is permitted by any of the cams, but must also have an excess of power so that 100 the roller 123 is promptly shifted at the proper time. By the provision of a pair of complementary rollers the returning spring is done away with and there results less of an interference with the motion of the carriage than in the arrangement employing a returning spring. I therefore have shown as the preferred embodiment of my invention the complementary rollers 123 and 128, but obviously a returning spring attached 105 to the bell crank may be used instead of the complementary system of rollers herein described.

The platen 39 is mounted on the typewriter carriage 166, which moves at right angles to the plane of the paper (Fig. 2) in suitable bearings 167 and 168 rigid in the framework. The typewriter carriage is urged to the left (Fig. 1) by the customary 110 spring tension arrangement (not shown) and this motion is controlled by the typewriter feed pinion 169, whose motion is controlled by the twin escapement wheels 48, previously referred to. The escapement is 115 of the well-known Remington form and need not be further described.

The typewriter carriage 166 is provided with a pair of forwardly-extending brackets 170 and 171, which serve to support the cam bar 172 by screws 173 and 174, which 120

125

engage elongated slots 175 and 176 in said cam bar, to the end that while said cam bar is permitted no freedom of motion parallel to the line of advance of the typewriter carriage 166, it may have motion in a plane at right angles thereto. On account of the elongated nature of the slots 175 and 176, it is necessary to support the cam bar at an intermediate point and to this end I have 10 provided a stud 177 rigid in the framework of the machine, said stud serving as a support for a pair of rollers 178 and 179 (Fig. 2). Said rollers are independently mounted on the stud 177, that is, the rollers 178 and 179 may each turn independently of the other.

The stud 177 (Fig. 2) is provided with an eccentric bearing in the actuator casting 281 and is held in its position by a locknut 289. This construction is for the purpose of permitting a vertical adjustment of the stud 177 to bring the rollers 178 and 179 into a position for the proper action of certain cams hereinafter to be described on 25 the complementary rollers 123 and 128.

The cam bar 172, whose center section is clearly shown in Fig. 9, is provided with a pair of V shaped ways 180 and 181, and consequently is thereby constrained by the 30 stud 177 against motion in any direction except parallel to the motion of the typewriter carriage 166. The result of the arrangement just described is that the cam bar 172 floats on the stud 177 and is exactly 35 constrained by said stud and associated rollers only at the point in which said cam bar is in contact with the rollers 178 and 179. At any other point the cam bar has a freedom of motion in a plane at right angles to the direction of motion of the carriage. The stud 177 is located directly above the point of action of the complementary rollers 123 and 128, and I am thus able to maintain the distance between said rollers 40 and the cams which actuate them with great exactness. It is obvious that the said distance will not be altered by accidental distortions of either the typewriter carriage 166 or the supporting brackets 170 and 171.

I will now describe the mountings for the cams which actuate the complementary rollers 123 and 128: Mounted on the cam bar 172 are a series of supporting frames 182, perspective views of which are given in Figs. 12 and 13, although views of the frames are shown in other figures, for example, Figs. 1, 3, 5 and 9. These frames consist of a pair of side plates 183 and 184, which are held together by tie plates 185, 55 186, 187 and 188, riveted in the side plates. Extending between the side plates are also a pair of tie rods 189 and 190. The cam bar 172 has a fin 191 (Figs. 1, 3 and 5) having a series of locating teeth 192 cut in the bottom thereof. These teeth are located one-

tenth of an inch apart, the pitch of the typewriter escapement, and by their engagement with suitable notches 193 and 194 in the sideplates 183 and 184 serve to locate the frames 182 in a definite position on the cam bar 172. The side plates 183 and 184 are held in engagement with the teeth through the medium of a pair of levers 195, which are rotatably mounted on the tie rod 190 and drawn downwardly by the tension 70 springs 197 and 198, extending between the levers 195 and the tie rod 189. The levers 195 are provided with undersurfaces 199 and 200, which are adapted to contact with the upper surface of the cam bar 172 and thereby hold the plates 183 and 184 securely 80 between the locating teeth 192.

In case it is desired to shift the location of the supporting frames 182, it can be easily 85 done by pressing on the top bar 185. The springs 198 and 199 will yield, thus permitting the sideplates 183 and 184 to become disengaged from the teeth 192. The frame 182 may then be slid along the bar 172 and be re-located in another position.

The frames 182 form supports for a set of cams 201 which serve to operate the complementary rollers 123 and 128, and it is one of the objects of my invention to make these cams so that they will be readily adjustable, that is, that the same cam may be adjusted to position the rollers in a position corresponding to the addition, subtraction or disconnect positions of the gear shift rod 85 as may be desired. Referring particularly to Fig. 13, a cam 201 is shown disassembled from its supporting frame. It will be noted that this cam consists of a block in which are two screw holes 202 and 203, which are adapted to be held by the screws 204 and 205, which join the tie plates 186 and 187. The cam 201 has a projection, or fin, 206, said fin being so positioned that when the cam 201 is mounted in the frame 182, the fin 206 will engage either the roller 123 or the roller 128, as the case may be. The block 201 is also provided with a surface 207, which is placed at a distance equal to the motion of one of the rollers 123 or 128 from the surface of the fin 206. If 100 the machine is to operate in addition, the fin 206 is so placed that it will contact with the roller 128, the roller 123 being raised to contact with the complementary surface 207. In case it is desired to operate in subtraction, the screws 204 and 205 are withdrawn and the cam 201 is taken from the frame and turned end for end and then replaced in the frame 182. The fin 206 will 105 then contact with the roller 123 and depress the same, thus throwing the gear shift rod 85 into its subtraction position.

A disconnect position of the gear shift rod 85 corresponds to the position in which the complementary rollers 123 and 128 are at 110

the same level. I have therefore provided a plane top surface 208 for the cam 201, and in case it is desired to have the gear shift rod 85 in its disconnect position corresponding to the calculating zone determined by the frame 182 the cam 201 is turned with the fin 206 uppermost. Both the rollers 123 and 128 then contact with the surface 208 and the gear shift rod 85 is accordingly brought into its disconnect position. It will be observed that this arrangement makes a very convenient way of changing the program of calculation as determined by the various cams 201 with which each of the frames 182 is provided. In order to change the cam from addition to subtraction it is simply necessary to remove the screws 204 and 205 and turn the cam 201 end for end and replace it. If it is desired to change from an addition or subtraction position of the cam 201 to the disconnect position of said cam, it is only necessary to withdraw the screws 204 and 205 and turn the cam 201 up side down. I consider this adjustable cam arrangement of great utility, since it avoids on the one hand the necessity of making a fixed cam extending the entire length of the cam bar 172 and on the other the necessity of having separate pieces or cams 201 for the different set-ups of addition, subtraction or disconnect. In my improved construction herein disclosed, by the use of a single cam, which is changeable to three different positions, I am enabled to obtain all of the possible positions of the complementary rollers 123 and 128.

The frames 182 also serve as a support for two other members whose functions will now be briefly described: The first is a pick-up 40 209 for the jumping totalizer. This is accomplished by extending the lower portion of the side plate 183 beyond the side plate 184, thereby forming a pick-up lug 209, said lug being adapted to pick up the jumping totalizer at the various zones of calculation, as will hereinafter be more fully described.

The tie plate 188 has its lower surface adapted to contact with a third roller 210, 50 which is pivoted on a bell crank 211, which rotates on the stud 121 and has for its object the operation of a certain interlock between the keys and the jumping totalizer. For the sake of clearness, explanation of the operation of this interlock is deferred to a later portion of this specification.

From what has gone before, it will be obvious that each frame 182 serves as a support, first for the cam which determines 60 the position of the gear shift rod 85 during the particular calculating zone delimited by the frame 182. Second, as a support for the pick-up lug 209, which serves to bring the jumping totalizer into action when the typewriter carriage is passing through the

zone defined by the position of the frame 182. Third, as a support for the cam 188, which serves to operate a certain interlock hereinafter to be described, between the jumping totalizer and the digit keys 31. It is obvious that the frames 182 can be readily adjusted to any desired location on the cam bar 172 and that the engagement of the depressions 193 and 194 between the locating teeth 192 will serve to hold the frame firmly in its adjusted position. It will also be noticed that adjusting the position of the frame 182 simultaneously adjusts the positions of all the instrumentalities necessary to bring the jumping totalizer properly into action in the calculating zone corresponding to the new position of said frame.

The ends of the cam bar 172 are cut away, as shown in Fig. 3, that is, the locating teeth and the V-shaped sections engaging the rollers 178 and 179 do not extend the entire length of the cam bar 172. Consequently, the frames 182 may be taken off of the cam bar 172 without the necessity of disconnecting said cam bar from the typewriter carriage. This is accomplished by sliding the frames 182 to the ends of the cam bar 172, whose width at that point is less than the dimension marked 212 in Fig. 12. The frames 182 may then be readily removed from the cam bar and the cams 201 may be adjusted to any desired position. This arrangement makes a very convenient method of making a set-up for the machine.

The supporting frames 182 may be of any desired width to correspond to the width of the zone or column of calculation. It is obvious that a frame 182 with its associated cam and pick-up will serve for a calculating zone which is narrower than the width of the frame so long as the calculating zones are not closer together than the width of said frame, that is, so long as the calculating zones do not overlap the frames. In this latter event it will of course be necessary to have a frame 182 which is narrow enough not to overlap the adjacent calculating zone.

The carriage and pick-up mechanism for the jumping totalizer and the jumping totalizer 220 are mounted on a truck 221 which slides in ways 222 and 223 cut in the front upper part of the actuator castings 281, which serves as the support for the actuator mechanism. The truck 221 has a dovetailed section 225 which corresponds to the usual section of the truck of a Wahl machine. This is for the purpose of accommodating the machine to the use of a standard Wahl totalizer. The section of a sliding truck may be clearly seen in Fig. 9. The front portion of the truck is provided with a plate 226 having a locating notch 227 therein, into which engages a latch 228 normally present on the Wahl totalizer, said latch 120 125 130

serving to hold the totalizer 220 securely in its located position on the truck. On the bottom of the truck 221 is a rack 229, having teeth 230 therein and the master dog 61 has a rearwardly extending portion 231 which is adapted to engage said teeth while the master dog is in its rocked position. This is for the purpose of forming a truck lock to prevent displacement of the truck 221 relative to the actuating mechanism while one of the digit keys 31 is being operated. The truck 221 has a pair of rearwardly extending portions 233 and 234, said portions having V-shaped slots therein forming the bearings for a series of balls 235 which run in the ways 222 and 223, thus providing an antifriction bearing for the truck 221. The balls 235 are provided with a suitable retainer 236, which is bent in a U-shaped section so as to embrace both the balls of the upper bearing 234 and the lower bearing 233, and said retainer has teeth 237 cut on its upper edge. A gear 238 is mounted on a stud 239 in the casting 281 and said gear has rigid with it a pinion 240 of half of the number of teeth. The pinion 240 engages the teeth 237 and the gear 238 is engaged by a series of rack teeth 241 cut on the upper edge of the truck 221. The ball retainer 236 consequently moves at half of the rate of the truck 221, thus maintaining the balls 235 in their proper positions.

The truck 221 is maintained in its normal position by means of a tension spring 242 which extends from a stud 243 in the casting 281 around a pulley 244 rotatively mounted on a stud 245 in the casting 281. The other end of the spring 242 is fastened to the truck 221 and thus serves to maintain the truck in a normal position determined by a stop 246 rigid with the framework of the machine. In case the totalizer truck 221 is picked up by any of the pick-ups 209 the truck 221 will move to the left step by step with the typewriter carriage until, by mechanism hereinafter to be described, the truck 221 is released from the typewriter carriage and the spring 242 then returns said truck either to its normal position or to a position determined by the next succeeding pick-up 209 on the cam bar 172.

I shall now describe the mechanism by means of which the pick-ups 209 engage and carry along the truck 221: This mechanism is most clearly shown in Figs. 7, 9, 11 and 12, reference to which will disclose that on the right end of the truck 221 (Fig. 11) is a plate 247 which serves to provide a pivot hole for a pivot 248 on a rear latch 249. Said latch is provided with a second pivot 250 in line with the pivot 248 and the second pivot has a bearing in a lug 251 rigid in the back of the truck 221. In line with the pivot 250 and having a bearing

in the same pivot hole is a pivot 252 on a front latch 253. Said latch is provided with a second pivot 254, which has a bearing in a lug 255 also on the inside of the truck 221. The rear latch 249 is provided with a spring 256 extending between said latch and a stud 257 in the truck 221. The front latch 253 is also provided with a spring 258 attached to a stud 259 in the truck 221 (Fig. 12). A stop plate 260, rigid with the truck 221, determines the normal position of both the front latch 253 and the rear latch 249.

The front latch 253 is provided with an inclined surface 261, and the rear latch is also provided with an inclined surface 262. These are provided for the purpose of allowing the pick-up 209 to ride over said latches and depress them when said pick-up approaches the latches from either direction. A disconnecting cam 263, (Figs. 4 and 12) having an inclined surface 264, is provided on the framework of the machine and contacts with the beveled surface 261 of the front latch 253 and serves to depress the same, thereby moving the front latch 253 out of its engagement with the pick-up 209, this disconnection taking place when the totalizer is one space to the left of its sub-unit decimal place.

The rear latch 249 is controlled by a lever 265, which is pivoted on a stud 266 on the truck 221 and has a nose 267 which is adapted to contact with the rear latch 249 and a nose 268 which is adapted to contact with a sliding piece 269, which slides on pins 270 and 271, which are set in an adjustable rack 272 rigid with the truck 221. The rear or right-hand end 273 of the plate 269 contacts with an upwardly-extending end 274 of a lever 275 pivoted on a stud 276 in the framework of the machine. The end 274 of the lever contacts with the stud 246, previously referred to. The engagement of the plate 269 with the pins or studs 270 and 271 is by means of inclined slots 277 and 278. When the spring 242 draws the truck 221 to its normal position, the contact of the ends 274 and 273 with the stop 246 elevates the plate 269, which in its turn elevates the lever 265, which elevates the front end of the latch 249 and depresses the rear end of the same out of the path of the pick-up 209. However, as soon as the pick-up 209, by its engagement with the front latch 261 has moved the carriage 221 from its normal position, the spring 256 moves the sliding piece 269 to the right (Fig. 12) and rotates the rear latch 249 into a position determined by the stop plate 260 and thus the pick-up 209 is securely held between the latches 253 and 249. This condition persists until the travel of the typewriter carriage has brought the bevel 261 of the front latch 253 into engagement with the bevel 264, when the front

latch 253 is depressed from its engagement with the pick-up 209 and the spring 242 starts to move the truck 221 to the right (Fig. 3). During all this time the rear latch 249 is of course in its elevated position and if during the righthand movement of the truck 221 just described the latch 249 encounters a succeeding pick-up 209, said pick-up will encounter the bevel 262, thereby depressing the rear latch 249, and will engage the front latch 261, which had by that time returned to its elevated position. Said next succeeding pick-up 209 will thereupon be securely held between the front latch 261 and the rear latch 249 and any bouncing or vibration of the truck 221 will be effectually prevented.

The necessity for holding the rear latch 249 in its depressed position when the truck 221 is in its normal position arises from the fact that when the typewriter carriage is returned for the beginning of a new line all of the pick-ups 209 are of course moved to the right. Should the latch 249 be allowed to remain in its upper position, it is obvious that this motion of the carriage would be prevented. I have therefore arranged the mechanism so that when the truck 221 is in its normal position the rear latch 249 will be held out of the path of any of the pick-ups 209. As soon as the truck 221 leaves its normal position the rear latch 249 will of course move to its upper position, thereby securely connecting the truck 221 with the typewriter carriage 166.

As before noted, there is a series of the pick-ups 209 on the cam bar 172 and by means of the mechanism just described when the typewriter carriage enters the zone of calculation delimited by a frame 182, the pick-up 209 will connect the truck 221 with the typewriter carriage and the two will move step by step together until the end of the calculating zone has been reached, when the incline 261 on the front latch 253 will encounter the incline 264 on the disconnect cam 263. At this time the truck 221 will be released from the lug 209 and said truck will return to the right until it reaches either its normal position or the next succeeding lug 209, when the truck 221 will be again connected to the typewriter carriage. By this mechanism I am enabled to define a succession of calculating zones during a single run of the typewriter carriage and also insure that the truck 221 shall be securely held to the typewriter carriage while said carriage is in a calculating zone.

The totalizer.

The totalizer used in my herein described invention is a modification of the totalizer described in my issued Patent No. 1,202,763, October 24, 1916. However, the totalizer described in said patent has been modified in

several very important particulars. Said modifications may be best understood from Figs. 9, 15, 16, 18 and 19, reference to which will disclose that the totalizer mechanism is contained between two side plates 301 and 302, which are adapted to be slidably mounted upon the truck 221 and held in their position by the latch 228 previously referred to. As distinguished from the ordinary Wahl totalizer, my improved totalizer contains two sets of numeral wheels, one set 303 being adapted to show positive quantities and the other set 304 being adapted to exhibit negative quantities. These totalizer wheels are so arranged in the totalizer that their numbers run in opposite directions and the totalizer cover or casing 307 is provided with windows 305 and 306, through which the numbers exhibited by these number wheels may be read. The interior mechanism of the totalizer, with the exception of certain members in the highest and lowest decimal place thereof, is substantially that of the well-known Wahl totalizer thoroughly described in the issued patent to John C. Wahl, No. 893,719, July 21, 1908, and in various subsequent patents to the same inventor. These totalizers have been extensively marketed under the name of the Remington-Wahl adding typewriter, and therefore need not be described in detail. It may be said in general that they consist of a set of gear wheels 308 (Figs. 16 and 17) which serve to actuate a series of idle gears 309, which are rotatably mounted on the shaft 310 extending between the side plates, the gears 309 being kept separated by suitable washers 311, and each of the idle gears 309 meshes with gears 312 and 313 rigid with the number wheels 303 and 304 respectively. The gears 308 are rotatably mounted on a shaft 314, supported between the side plates 301 and 302, and said gears are connected by the usual Geneva gears 315 and 316 of the Wahl totalizer.

These Geneva gears are mounted on swinging arms 317 and 318, said arms being lifted from their position seriatim by the action of the master dog 61, which it will be recalled rocks in a counterclockwise direction (Fig. 9) prior to the insertion of each digit of the number.

The numeral wheels 303 and 304 are paired in the relation 9 to 0 (Fig. 19), that is, when the line of zeros on the wheels 303 is opposite the window 305, then the wheels 304 will have a line of 9s opposite the window 306. As thoroughly described in my issued patent, it is necessary that in passing through zero in an algebraic totalizer an additional unit be added in the lowest place of said totalizer. I shall not go into an explanation of why this is necessary, since a full explanation of it is contained in my cited Patent No. 1,202,763, to which the reader is referred. The insertion of this unit in my present

invention is accomplished not by means of a handle, as is done in my cited patent, but by means of the master wheel 54 and the special key 50. The mechanism connected to 5 said key will hereinafter be fully described.

Referring to Fig. 18, in which is shown a perspective view of the parts of my improved totalizer, it will be noticed that at the right of the lowest decimal place of the 10 totalizer there is present a segmental gear 319 having a slot 320, which is adapted to engage a stud 321 rigid to the sideplate 301, the relation between the width of the slot 320 and the width of the stud 321 being 15 such that a one tooth motion only of the segmental gear 319 is permitted. The segmental gear 319 is provided with a set of teeth 322, which are adapted to be engaged by the master wheel 54 when the totalizer 20 arrives at the place to the right of the last decimal place of the totalizer. I shall hereinafter call said place the sub-units place. The segmental gear 319 has also a set of teeth 323 which engage with an idle gear 25 324, which like the Geneva gears of the totalizer is mounted on a swinging arm and serves to transmit motion to the wheel 308 in the lowest decimal order of the totalizer. Consequently, if the segmental gear 319 is moved 30 one step, the gear 308 in the lowest order of the totalizer is moved one step also; it is by means of the gears 319 and 324 that a unit is inserted in the last decimal place of the totalizer, since at the time said insertion 35 is made the master wheel 54 is in engagement with the segmental gear 319 in the sub-units place of the totalizer. If the insertion of the unit entails any carrying to wheels 308 of higher order said carrying will take 40 place since the carrying chain is at that time completed up to and including the highest decimal order of the totalizer.

The segmental gear 319 is provided with a finger 325, which engages a fork 326 in a 45 rocker 327 rotatably mounted on the shaft 310. The rocker 327 has two fingers 328 and 329, which engage forks 330 and 331 in shutters 332 and 333. Said shutters are made in the form of a bail and are rotatably mounted on the shafts 334 and 335 which serve to support the number wheels 50 304 and 303 respectively. Obviously, if the segmental gear 319 is turned one step, both the shutters 333 and 332 will be thrown to 55 their alternate positions. Each of these shutters is provided with a window 336 and 337 through which the number wheels may be read. When the totalizer is exhibiting positive numbers, the parts are in the position as shown in Figs. 18 and 19, that is, the 60 figures on the numeral wheel 303 may be viewed through the window 305 in the casting and the window 337 in the shutter 333. The numbers on the negative numeral wheels 65 304 are concealed by the shutter 332 and also

by a shutter 338, which is likewise made in the form of a bail and is arranged to extend over the outside of the shutter 332, and is rotatably mounted on the shaft 335. Similar to the shutter 338, cooperating with the 70 number wheels 304, I have provided a shutter 339 cooperating with the number wheels 303 and rotatably mounted on the shaft 335. The two shutters 338 and 339 are adapted to be actuated by the gear 308 in the highest 75 order of the totalizer in the following manner.

When said gear carries, the Geneva gear associated with it moves a segmental gear 340, which is rotatably mounted on the shaft 80 314, and said gear has a finger 341 rigid therewith, which engages a fork in a rocker 342 rotatably mounted on the shaft 310 and which has fingers 343 and 344 which engage 85 forks 345 and 346 in the shutters 338 and 339. Obviously whenever the highest wheel of the totalizer carries, that is, whenever the totalizer passes through zero in either direction, the shutters 338 and 339 are shifted to their alternate positions. The 90 segmental gear 340 has in it a slot 347, which engages a pin 348, which is riveted in the sideplate 302. The widths of the slot 347 and the stud 348 are so proportioned that the segmental gear 340 has possible motion of only one step. It is necessary to provide this check in order to avoid straining the shutters by operating the totalizer beyond its capacity.

The method of operation of the totalizer 100 is as follows: Starting with the parts in the position shown in Fig. 18, numbers are added in the totalizer and will be exhibited on the wheels 303, the numbers on the wheels 304 being concealed both by the shutter 332 105 and the shutter 338. If, however, a number greater than the number exhibited on the wheels 303 is subtracted from the totalizer, the highest wheel of the totalizer will of course carry, which will actuate the segmental gear 340 and consequently shift the shutters 338 and 339 to their alternate positions. When the totalizer is in this condition, no 110 number is visible. However, the shutters are provided with legends, as shown, and the totalizer will then exhibit the following legends: "Overdraft" on the shutter 339 and "Subtract one" on the shutter 332. The two shutters 332 and 339 will of course change 115 position coincident with the insertion of the first digit which causes the totalizer to pass through zero. For instance, if the totalizer stood at 426 and one were to insert 532, the shutters would change position coincidently with the insertion of the 5. When the digit 120 has been inserted in the last decimal place of the totalizer, the truck 221 on which it is mounted escapes one step to the left, so that the totalizer is engaged with the master-wheel 54 in the sub-units place, the master 125 wheel 54 in the sub-units place, the master

wheel 54 being then in engagement with the teeth 322. The special key 50 is then operated according to the visible instruction "Subtract one." This subtracts a unit from 5 the lowest place of the totalizer and coincidentally shifts the shutters 332 and 333. The numbers on the wheels 304 are now visible and there is displayed by the totalizer the correct negative total 106 and also the 10 legend "Overdraft," thus indicating that the number exhibited is an overdraft.

I consider the instructions of "Add one" and "Subtract one" very important, since it is evident that the totalizers may be 15 closed, no numbers being visible and the operator would be in ignorance of which way to operate the same in order to render a number visible. It is therefore necessary to have the legends on the shutters, since if 20 these legends were absent and a totalizer did not exhibit any number, the operator would be in absolute ignorance in which direction to operate the totalizer to insert the extra unit in order to have a number exhibited. 25

Mechanism connected with the special key 50.

As noted in the previous chapter, the 30 function of this key is to insert or withdraw a number from the units decimal place of the totalizer in the event that the numbers previously inserted have caused the totalizer to pass through zero. Referring particularly to Figs. 1 and 2, it will be observed 35 that the special key 50 has riveted to it a U-shaped extension 360, to which is attached a pull-rod 49, which leads to a fan 52, similar to the other fans in the actuator. The fan 40 52 has associated with it a gooseneck 74, which engages a roller 75, so set as to rotate the sector shaft 77 but one step. Fig. 2 has been so broken away, and in Fig. 9 the section has been so taken as to show the parts 45 just described. The depression of the special key 50, has, as far as rotation of the master wheel is concerned, the identical effect that a depression of the one digit key has, that is, the master wheel is rotated one step in a 50 direction determined by the position of the gear shift rod 85. Now it so happens that, when a number is subtracted from the totalizer greater than the number exhibited by the totalizer thus causing the totalizer to 55 pass through zero and change its sign, the extra unit which has to be inserted to correct the total must be inserted in the same direction as the number which causes the totalizer to change sign. In view of this 60 fact, in case the insertion of any number into the totalizer causes the disappearance of the exhibited number from the totalizer by reason of the moving of the shutters 338 and 339 to their alternate positions then it 65 is necessary to operate the key 50 when the

totalizer reaches the sub-units place. The unit to bring the totalizer to the proper reading will then be inserted in the same direction as the number which causes the totalizer to change its sign. 70

The above is true whether the totalizer contains a positive number and a greater negative number is inserted therein or whether the totalizer contains a negative number and a greater positive number is inserted therein. The rule holds good in both cases. Therefore, it is not necessary to pay any attention to the position of the gear shift rod 85 when operating the special key 50, if said operation is done immediately 80 after the insertion of the number which causes the totalizer to change sign. The fact that the totalizer has changed sign, is indicated by both sets of wheels 303 and 304 being covered by shutters. 85

I consider the provision of inserting a number by means of the special key 50 in the sub-units decimal place of great importance. It simplifies some operation difficulties arising from faulty manipulation by the operator which arose in connection with use of the totalizer described in my issued Patent No. 1,202,763 supra. For instance, in the totalizer described in said patent, if the operator shifted the handle when the totalizer was in engagement with the master wheel, it was possible that carrying might take place including the wheel in mesh with the master wheel. This, of course, would render operation of the handle impossible and if the operator strained this handle in an endeavor to operate it, breakage might result. In my herein described form this difficulty, due to misoperation, is impossible, since at the time the unit is inserted the master wheel 100 105 110 115 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450 455 460 465 470 475 480 485 490 495 500 505 510 515 520 525 530 535 540 545 550 555 560 565 570 575 580 585 590 595 600 605 610 615 620 625 630 635 640 645 650 655 660 665 670 675 number of wheels in which the spiral could be corrected. I am now referring to totalizers which were adaptable for commercial sale and use. However, in my herein described device I am able to use a totalizer and in fact have constructed the same with a capacity as high as seventeen decimal places. I see no reason why this number of decimal places could not be exceeded if the same 10 were necessary, since the master wheel will clean up any spiral resulting from a totalizer of large capacity.

The special key 50, as will be seen from the above description, is operated only when 15 the totalizer is in the sub-units decimal place and in no other position. On the other hand, the digit keys 31 are not operated when the totalizer is in the sub-units position. Since it is possible to insert but one 20 unit into the totalizer in the sub-units place, the operation of any of the digit keys 31 in said place (except the one-key) would result in tying up the machine. It is therefore desirable to provide an interlock to prevent 25 improper key operations in respect to this mechanism. This interlock is accomplished by the following mechanism:

Referring particularly to Figs. 2, 4, 8 and 9, it will be seen that each of the fans 30 52 is provided with a nose 349, which is adapted to enter between the members of the single-key mechanism. This mechanism consists of a series of cams 350, 351, 352, 353, 354, 355, 356, 357, 358, 359 and 361, 35 which are so contained between the framework of the machine that in the entire series of cams there is a space equal to the width of one of the fans 52. On the cam 350 there is a pin 362 which engages a slot 363 in the framework. The cams 350 to 359 inclusive and 361 are all pivoted in the framework on shafts 364. The cam 359 has rigidly mounted thereon a pin 365, which is engaged by a slot 366 in a hanger or pendant 367, which is pivoted at 368 on the lever 369, rotatably mounted on the stud 370 rigid in the framework.

Passing for a moment the action of the lever 369, the hanger 367 has in it a slot 373 50 which engages a pin 372 rigid in the cam 361. When the hanger is in the position shown in Fig. 4 the single-key mechanism consisting of the cams 350 to 359 inclusive is constrained by the pin 362 and slot 363 55 on one end, and the cam 361, which contacts with the framework so that in the entire series of cams there is but space equal to the thickness of a fan 52. When in this condition any one of the digit keys 31 may be 60 operated, since the cams as a whole have free space equal to the thickness of one of the fans 52 between the contact of the pin 362 with the wall of the slot 363 and the cam 361 with the framework. If, however, the 65 hanger 367 should be lowered, the pins 365

and 372 will engage the upper portions of the slots 366 and 373, which are wider apart than the lower portions by the width of a fan 52. This will close the single key mechanism as far as the fans corresponding to 70 the digit keys 31 are concerned. However, the lowering of the hanger 367 will separate the cams 361 and 359, which heretofore have been held in contact with each other, for a distance sufficient to allow the operation of the fan 52, connected with the special key 50.

It is pointed out that the zero key is connected to the fan 52 at the extreme left of Fig. 4 and that the operation of this zero 80 key is permitted while the hanger 367 is in the position shown in Fig. 4, since said hanger, in case the zero key is operated, will simply pivot around the stud 368 and thus swing the two cams 361 and 359 to the right 85 and thus prevent the operation of any of the other numeral keys 31.

I will now describe the means by which the lever 369 is actuated to depress the hanger 367 when the totalizer arrives at the 90 sub-units decimal place: Referring to Fig. 1, it will be noticed that the rack 229 has on it a hump or cam 374, and when the totalizer is in the said sub-units decimal place said hump depresses a roller 375 (Figs. 3, 95 8 and 14) which is mounted on a lever 376 rigid to a shaft 377 pivoted in the framework and having attached to the rear end thereof a lever 378 (Fig. 4), which contacts with a pin 379, mounted in the lever 369. A spring 380, between the lever 378 and the framework, serves to maintain said lever in a position determined by its contact with the pin 379, whose normal position is determined by the contact of the lower ends of the slots 373 and 366 with the associated pins 372 and 365. When roller 375 is depressed, arm 378 moves upward and pendant 367 drops down by gravity, which may be assisted by a spring if preferred. 100 From this arrangement it results that the special key 50 will be locked and the digit keys 31 unlocked at all places of the totalizer except when the totalizer is in the sub-units decimal place. At that time all the digit 105 keys of the machine will be locked and the special key will be unlocked so that it may be actuated in case the number just inserted has caused the totalizer to pass through zero.

It sometimes happens that the operator tries to operate the gear 319 by the special key 50 in the wrong direction, in which case the rotation of the segmental gear 319 is prevented. In this event the adding machine 110 will become locked up by reason of the fact that the downstroke of the key has progressed far enough before the mechanism was stopped for the full-stroke pawl 56 to engage the teeth 59. Further down- 115 120 125 130

ward motion of the key 50 is prevented by the stud 321 and further upward motion will be prevented by the full-stroke pawl 56. It is necessary therefore to provide some means of unlocking the machine under the conditions referred to. The same means is also useful in case a regular numeral key 31 has been partially depressed and it is desired for any reason to restore it to normal without completing its down stroke.

To this end I have provided a release lever 381, Figs. 1, 4 and 5, which is pivoted to the framework of the machine by a stud screw 382 and is held in a normal position defined by a stop 383 by a tension spring 384 extending to a stud screw 385 rigid to the framework. At the time the machine is locked, as previously explained, the front full-stroke pawl 56 prevents the return of the key to its normal position. However, at this time the rockshaft 69 has been displaced from its normal position and, in the case of a partially depressed numeral key 31, the sector shaft 77 may have been displaced from its normal position. In order to avoid errors, it is necessary to return these parts in a certain sequence. Otherwise if the rockshaft 69, for instance, were returned to its normal position prior to the return of the sector shaft 77, the shiftable plate 80 might withdraw the sector 78 from mesh with either the direct or reversing gear before the sector shaft is returned to its normal position. Consequently a less number will be rolled out of the totalizer on the up-stroke of the key on the return of the sector shaft than was rolled into it on the forward motion of the sector shaft and error will result. It is therefore necessary to make the action of the lever 381 such that the rockshaft is prevented from returning to its normal position until the sector shaft has been returned to its normal position and has been locked on the usual latch 386 (Fig. 22) customarily present in the Wahl actuator. It is further necessary, in order to guard against errors in the operation of the lever 381, to prevent the operation of any other digit key during the return of the displaced key to its normal position or even during the return of the rockshaft and sector shaft to their normal position. To this end I have provided in connection with the lever 381 an interlock which is adapted to cooperate with the single key mechanism, to the end that as soon as the partially depressed key is disengaged from the single key mechanism this interlock will enter said mechanism, thereby preventing the operation of any other key until all the parts affected by the lever 381 have been returned to their normal position.

Referring now to Figs. 4 and 14, which best illustrate the actions of the parts connected to the lever 381, it will be observed

that said lever is provided at its righthand end (Fig. 5) with a stud screw 387, which extends through said lever and is adapted to contact with a cam 388, which is rigid with the front full-stroke pawl 56. Consequently, when the lever 381 is operated, the stud 387 will contact with the cam 388 and lift the front full-stroke pawl from its engagement with the teeth 59 of the fan 52. This will permit said fan to return to its normal position and the partially-depressed digit key 31 or special key 50 connected therewith to return to its normal position. The lever 381 is provided with a cam surface 389, which cooperates with a pin 390 attached to an arm 391 rigid to the rockshaft 69. It will be observed that as long as the rock shaft is in its normal position operation of the lever 381 is prevented by the pin 390. However, when any fan 52 is operated by a digit key the first part of the motion of said fan will shift the rockshaft 69 to its displaced position by the action of the heel 71 on the bail 70. Therefore, the rockshaft 69 must be thrown to its displaced position before the lever 381 may be operated at all. That is, the lever 381 cannot be operated unless a key, either a digit key or the key 50 is partially depressed. The cam surface 389 terminates in a point 392 and since the lever 381 cannot be operated until the pin 390 has passed the point 392 I have provided a second cam surface 393 on the lever 381 for the purpose of holding the pin 390 and consequently the rigidly attached rockshaft 69 in its displaced position during the time when the lever 381 is displaced. The lever 381 is provided on its upper portion with a catch 394, cooperating with which is a detent 395 pivoted on a stud screw 396 rigid to the framework. The detent 395 has a tail 397 which is adapted to be acted on by a pin 398 mounted in an arm 399, which is attached by a screw 400 to the sector shaft 77 and moves rigid therewith. The operation of the lever 381, as far as the previously recited parts are concerned, is as follows:

Assume a key has been partially depressed, motion of the rockshaft will have shifted the pin 390 from its position, as shown in Fig. 5, into a position where it will clear the point 392. The sector shaft 77 may also have been displaced from its normal position. The lever 381 may then be raised, thus releasing the front full-stroke pawl 56 by reason of the action of the stud 387 on the cam 388. However, when the lever 381 is thus raised, the rockshaft 69 is retained in its displaced position by contact with the pin 390 of the cam surface 393. The lever 381 is then released but the action of the detent 395 on the catch 394 prevents the return of said lever to its normal position, the rockshaft of course being still held in its displaced position. The return

of the sector shaft to its normal position through the spring (not shown) ordinarily present in the Wahl actuator will release the detent 395 by contact of the pin 398 with the tail 397. The lever 381 is then free to return to its normal position under the influence of the spring 384, and when said lever has reached its normal position the pin 390 will escape from the cam 393 and the rockshaft 69 will return to its normal position. In practice I have found it advantageous to place a manually operable handle 401 forming an extension of the arm 399. This is for the purpose of permitting the manual manipulation of the sector shaft 77 upon its return after being released by the lever 381, since it sometimes happens that the spring returning the said sector shaft is not strong enough of its own power to operate the detent 395. The cycle of operations under this arrangement, using the handle 401 is as follows: Upon one of the digit keys being struck, the lever 381 is pulled in a clockwise direction (Fig. 5) and then released. The lever 401 is then pressed in a counterclockwise direction (Fig. 5). This will release the detent 395, allowing the lever 381 to return to its normal position and the rockshaft 69 will then return to its normal position.

For the purpose of preventing the operation of a second digit key during the time the lever 381 is performing its function, I have attached a twisted link 402 to the stud 387, and said link is pivoted on a lever 403 having a hole 404 therein to avoid interference with the stud 368, from which is suspended the hanger 367, said lever 403 being pivoted on the stud 370, which also serves as a pivot for the lever 369. The righthand end 405 of the lever 403 (Fig. 14) is provided with a stud 406, which engages a slot 407 in a hanger or pendant 408, having a stud 409 riveted therein. A spring 410 is attached to said stud and the other end of said spring is attached to a stud screw 411 on the framework of the machine, so that the hanger 408 has a tendency to rise. (Fig. 14). Said hanger has a tail 412, which extends between the cams 356 and 355 and the mountings for the same, thereby constraining the motion of the hanger 408 to a motion in a vertical plane. The hanger 408 has in it a cutout portion 413, which is adapted to work between the cams 355 and 356 of the single key mechanism. The operation of this mechanism is as follows:

Whenever the lever 381 is operated, the stud 406 is withdrawn from the lower end of the slot 407, so that the hanger, if it were not otherwise held down, would be free to rise under the influence of the spring 410. However the fact of a nose 349 on the fan 52 of the partially depressed key being already engaged with the single key mecha-

nism will prevent this rise of the hanger 408 until said nose is free of its contacting arms whereupon the spring 410 will at once draw the hanger 408 between the cams 356 and 355. Thus the operation of any numeral key and of the key 50 will be prevented until the lever 381 has been returned to its normal position, in which event the stud 406 will depress the hanger 408 against the spring 410, thus removing the lock from the single key mechanism and permitting the operation of any of the numeral keys 31 or special key 50. The action of the hanger 408 forms a very efficient safeguard against the machine being operated with the lever 381 in its operated position, since it is evident that if the lever 381 is once displaced from its normal position all the parts of the machine must be restored to their normal position before the operation of any of the numeral keys is permitted.

The typewriter carriage lock.

I have already described a lock for the truck 221 to the end of preventing motion of said truck while any of the numeral keys were partially depressed. As long as the truck is connected to the typewriter carriage through the medium of the pick-ups 209 it is evident that locking the truck 221 will lock the typewriter carriage also. However, it may so happen that a numeral key may be partially depressed while a pick-up 209 is not connected to the truck 221, in which event the typewriter carriage itself would be free to move, and if it were moved until one of the pick-ups 209 contacted with either the back latch 249 or the front latch 253, breakage might result. It is therefore desirable to provide a lock which is independent of the lock for the truck 221 for the typewriter carriage. To this end (Fig. 1) I have provided the typewriter carriage with a rack bar 414, which is supported by extensions 415 and 416 from the brackets 170 and 171. The rack bar has a series of locating teeth 417 on the front portion thereof (Figs. 1, 4, 5 and 7) and said teeth are adapted to be engaged by a lever 418, which is pivoted on the framework at 419 and is guided between a form 420 rigid to the framework. The lower portion of the lever 418 (Fig. 5) is connected by a curved drag link 421 to an arm 422 on the rockshaft 69. Obviously every time the rockshaft is operated, that is, every time any of the numeral keys or the key 50 is operated, the lever 418 will engage the teeth 417 and lock the typewriter carriage so long as any of the numeral keys are depressed. It is therefore impossible to move the truck 221 out of its normal position by hand, and then depress a numeral key, thus holding the truck in its displaced position and then move the typewriter carriage, thus causing one of

the pick-ups 209 to violently contact with either the rear latch 249 or the front latch 253.

5 Interlock between the digit keys and the jumping truck.

During the course of entering numbers into the machine it is possible that the jumping truck 221 may become accidentally disengaged from a pick-up 209. Said truck would at once return to its normal position under the influence of the tension spring 242. If this return were not noticed and the operator continued to insert the digits of the number, an error would of course result. I have therefore thought it desirable to arrange an interlock between the truck 221, and the digit keys 31 and the frames 182, which define the calculating zone. The operation of this interlock is as follows:

1. In case a frame 182 is in a calculating zone and the truck 221 is in its normal position, the digit keys of the machine are locked.
2. In case a frame 182 is not in a calculating zone and the truck 221 is in its normal position, the digit keys are free to be operated.
3. In case the frame 182 is in a calculating zone and the truck 221 is not in its normal position, thus corresponding to the case in which the truck 221 has been picked up by a pick-up 209, the digit keys of the machine are unlocked.
4. A mechanism to attain the three ends outlined above will have the effect of preventing operation of the digit keys in case of an accidental disconnection of the truck 221 from the pick-up 209 when the frame 182 is in a calculating zone. However, operation of said digit keys when the frame 182 is not in a calculating zone or when said frame is in a calculating zone and the truck 221 is properly connected thereto will be permitted.

I shall now describe the means by which this interlock is accomplished: Reference to Figs. 3 and 9 will disclose that the rockshaft 69 is provided with an arm 423 rigid thereto, and said arm is adapted to enter a slot 424 in a stud 425 rigid in the framework each time the rockshaft 69 is operated. It will be remembered that the rockshaft 69 is operated by the heel 71 of one of the fans 52 whenever any of the digit keys or key 50 is operated. Consequently, locking the rockshaft 69 results in locking the digit keys and key 50 against operation. Adapted to swing over the slot 424 is a hanger 426 which is pivoted by a stud 427 to the lever 275 previously referred to, which is rotatably mounted on a stud 276 in the framework, as previously described, and is held in a normal position determined by a stud 435 on the framework by a spring 436.

On the rear end of a shaft 437 (Figs. 9 and 14) extending through the framework is attached a forked lever 428, which engages a pin 429 in the depending end 430 of a lever 431 which is pivoted on the stud 121 which serves as a support for the bell crank 120. It has been previously described that the horizontal arm 211 of the bell crank 430 has mounted on it a roller 210, which is adapted to be engaged by the cam 188 mounted in each of the frames 182. A spring 432 (Fig. 4) extending between a stud 433 in the framework and the bell crank 430 serves to maintain this system in a normal position as determined by a stop 434.

On the front end of the shaft 437 is an arm 438 to which is pivoted a link 439 which is pivoted to the pendant 426 (Figs. 3 and 13). The operation of this interlock is as follows: At any time when a frame 182 is in a calculating zone, the roller 210 will be depressed and consequently the lever 438 will be rotated in a clockwise direction (Fig. 3). This will pull the pendant 426 in the path of the arm 423. Consequently motion of any of the numeral keys will be prevented. If, however, the truck 221 has been displaced from its normal position, the lever 275 will be permitted to rise under the force of the spring 436. This will lift the pendant 426 vertically out of the path of the arm 423, and the operation of the digit keys will be permitted. Thus the pendant 426 is controlled from two independent sources: One is the position of the truck 221 and the other is the position of a frame 182 relative to the calculating zone.

The adjustable stop for the truck 221.

In order to accommodate various widths of totalizers it is desirable to provide an adjustable stop for the truck 221. As previously noticed, the normal place of the truck 221 is defined by contact of the end 274 of the lever 275 with the stop 246, and contact of the rear end 273 of the sliding piece 269 with the adjustable rack 272 and the end 274. The adjustable rack 272 is provided with a series of screw holes 440 and a series of locating notches 441, which latter are adapted to engage locating pins 442 and 443 in the rear of the truck 221 (Fig. 11). A series of numbers 444, designating the various spaces of the totalizer, are placed on the front side of the adjustable rack 272, and a sight opening 445 is provided in the truck 221 (Figs. 1, 3 and 11). The adjustable rack is held to the truck by a screw 446, which is countersunk in the truck and engages any one of the screw holes 440. It will be observed that the sliding piece 269 is adjusted at the same time as the adjustable rack 272 and therefore that proper action of the rear latch 249 will be maintained irrespective of the particular adjustment of the rack 272.

The typewriter is equipped with the customary color shift 447, which is of the construction usually present in the Remington typewriter. Referring to Fig. 1, it will be seen that the shift includes a shaft 448 having a lever 449 attached thereto. By means of said lever, the shaft 448 may be rotated and this determines whether the typewriter shall print in one color or in another, the usual arrangement being that when the shift is in the position shown in Fig. 1, the typewriter prints in black, and when the shift is placed in its alternative position defined by the arrow 450, pointing to the color block 451, the typewriter prints in red or some color readily distinguishable from black. The precise mechanism of this shift is not material to my invention, and therefore will not be described in detail. It will be sufficient to say that color shifts of this kind are well known in the art and have come into wide commercial use. The lever 449 is connected by a link 452 (Fig. 1) to the rear end 453 of the universal correcting lever 160. Therefore, when said lever is placed in its reverse position the color shift will be simultaneously operated and the typewriter will print in red, if such be the contrasting color employed.

The connection between the universal correcting lever and the color shift is of great importance, especially as used with an algebraic totalizer. In writing bank statements, it is desirable to have overdrafts, when the same occur, printed in a contrasting color to afford a striking indication of the existence of an overdraft. It so happens that with the algebraic totalizer herein disclosed an overdraft is cleared from the totalizer in the reverse manner in which a credit balance is cleared. Therefore, in clearing the totalizer when there is an overdraft the operator places the universal correcting lever 160 in its alternative position before starting to clear the totalizer by means of the digit keys. The shifting of the universal correcting lever 160 will simultaneously operate the color shift and therefore an overdraft will be printed in red as the same is cleared from the machine. The next time the operator handles the sheet, for instance as on the next day, it is of course necessary to pick up the previous day's balance. Inasmuch as this previous day's balance was an overdraft, it is necessary that it be entered into the machine in the reverse of the manner in which a prior day's credit balance is entered. The operator's attention having been attracted by the fact of the prior day's balance being printed in red, she will place the universal correcting lever 160 in its alternative position before picking up the prior day's balance. This will result in the simultaneous shifting of the color shift 447 and the printing of the balance which is

thereafter picked up in red, thus indicating that the balance was an overdraft. The fact that the universal correcting lever was shifted to its alternative position before said balance was entered into the totalizer of course insures that the balance shall be entered in the proper manner, and the fact that the two numbers in red appear on the sheet indicates that the machine has been operated in the correct manner to take care of the overdrafts in the particular customer's account.

I have described my present machine as being equipped with an algebraic totalizer and have given as an illustration of the use to which it can be put a problem requiring the use of an algebraic totalizer. However, it will be evident to those skilled in the art that my machine is by no means limited to use with an algebraic totalizer, since there are a large number of problems requiring the crossfooting of numbers in which a negative balance never occurs. It is of course possible to handle these problems on a machine equipped with an algebraic totalizer, since the totalizer, if of sufficient capacity, will function properly even if all the computations are confined to the positive number wheels. However, I wish to point out that my machine may be used in a large number of problems in which an algebraic totalizer is not employed.

It is of course understood that the typewriter associated with my herein described invention is provided with a set of tabulating keys for the purpose of rapidly advancing the typewriter carriage to the decimal place in which is written the first digit of the inserted number. I have not shown these keys in my present application, for the reason that the tabulator mechanism per se forms no part of my present invention and is well known in the art, especially in the particular form of the Gorin tabulator sold in connection with the Remington typewriter. The omission of this tabulating mechanism from the drawings of my herein described invention is simply for the purpose of somewhat simplifying these drawings. My herein described machine is so complicated and has so many parts that I believe the omission of well-known mechanism, such, for instance, as the tabulator mechanism, the ribbon shift mechanism, the details of the escapement mechanism, etc., will be helpful to the understanding of my invention, said mechanisms per se forming no part of my present invention, but only being useful in combination with the new mechanisms constituting my invention and forming parts of certain new combinations hereinafter claimed.

In a number of the claims I have used the term "number inserting mechanism" and I wish to be understood by this as a mecha-

nism which will insert a number greater than unity. I am well aware that there have been structures proposed in the prior art in which the unit necessary to correct the algebraic totalizer has been inserted by various mechanisms, for instance, the lever 42 of my issued Patent No. 1,202,763 and the key 30 of the Rinsch  Patent No. 1,179,564. However, by the term "number inserting mechanism" I wish to exclude such structures as are adapted to insert one unit only and wish the term "number inserting mechanism" to be limited to a mechanism which is adapted to insert a number greater than unity into a totalizer. I make this definition in the specification to avoid unnecessary prolixity in the claims in this case.

Many changes and modifications may be made in the precise structure herein disclosed without departing from the spirit of my invention, since I claim:

1. In a calculating machine, the combination of a totalizer, means to insert a number in said totalizer seriatim, either positively or negatively, means adapted to exhibit two sets of numbers in said totalizer, one set of numbers being adapted to exhibit positive totals and the other set being adapted to exhibit negative totals, means for concealing one or the other of said sets of numbers, and means operated by said number inserting mechanism and brought into action after the insertion of a number to insert an additional unit in said totalizer under certain circumstances, whereby the correct resultant of a series of positive and negative numbers may be exhibited.

2. In a calculating machine, the combination of a totalizer, means to insert a number in said totalizer seriatim either positively or negatively, means to indicate when said totalizer has been made to pass through zero, and means operated by said number inserting mechanism and brought into action after the insertion of a number to insert an additional unit in said totalizer subsequent to its passage through zero, whereby the correct resultant of a series of positive and negative numbers may be exhibited.

3. In a calculating machine, the combination of a totalizer, means to insert a number in said totalizer seriatim either positively or negatively, means adapted to exhibit two sets of numbers in said totalizer, one set of numbers being adapted to exhibit positive totals and the other set being adapted to exhibit negative totals, means for concealing one or the other of said sets of numbers, and means operated by said number inserting mechanism and brought into action subsequent to the insertion of a number to insert an additional unit in said totalizer under certain circumstances, whereby the cor-

rect resultant of a series of positive and negative numbers may be exhibited.

4. In a calculating machine, the combination of a totalizer, means to insert a number in said totalizer seriatim either positively or negatively, means to indicate when said totalizer has been made to pass through zero, and means operated by said number inserting mechanism to insert an additional unit in said totalizer subsequent to its passage through zero, whereby the correct resultant of a series of positive and negative numbers may be inserted.

5. In a calculating machine, the combination of a totalizer, means to insert a number in said totalizer either positively or negatively, a set of digit keys driving said number-inserting means, a special key also driving said number-inserting means, said special key being adapted when operated to insert a number in said totalizer, and means controlled by said totalizer to prevent an incorrect operation of said special key.

6. In a calculating machine, the combination of a totalizer, means to insert a number in said totalizer, either positively or negatively, a set of digit keys adapted to operate on said number-inserting means, a special key also adapted to operate on said number-inserting means, said special key actuating said number-inserting means to insert a single unit in said totalizer when said special key is operated, and means controlled by said totalizer to prevent an incorrect operation of said special key.

7. In a calculating machine, the combination of a totalizer, means to insert a number in said totalizer either positively or negatively, a set of digit keys adapted to operate on said number-inserting means, a special key being adapted to insert a single unit in either direction, said special key actuating said number-inserting means to insert a single unit in said totalizer when said special key is operated, and means controlled by said totalizer to prevent an incorrect operation of said special key.

8. In a calculating machine, the combination of a totalizer, means for indicating the positive resultant of a series of numbers inserted in said totalizer, means for indicating the negative resultant of a set of numbers inserted in said totalizer, number-indicating means to indicate whether said resultant is positive or negative, a set of numeral keys adapted to operate actuating mechanism, a special key also adapted to actuate said actuating mechanism, means operated by said actuating mechanism to insert a unit in said totalizer whenever said special key is operated, and means controlled by said totalizer to prevent an incorrect operation of said special key.

9. In a calculating machine, the combina-

tion of a totalizer seriatim, means to insert a number in said totalizer either positively or negatively, a set of digit keys operative on said number-inserting means, a special 5 key also operative on said number-inserting means, said special key being adapted when operated to insert a number in said totalizer, and means controlled by said totalizer to prevent an incorrect operation of said 10 special key.

10. In a calculating machine, the combination of a totalizer seriatim, means to insert a number in said totalizer either positively or negatively, a set of digit keys 15 adapted to operate on said number-inserting means, a special key also adapted to operate on said number-inserting means, said special key actuating said number inserting means to insert a single unit in said totalizer 20 when said special key is operated, and means controlled by said totalizer to prevent an incorrect operation of said special key.

11. In a calculating machine, the combination of a totalizer, actuating mechanism 25 adapted to insert a number in said totalizer seriatim, a set of digit keys adapted to operate on said number-inserting means, a special key being adapted to insert a single unit in either direction, said special key actuating 30 said number-inserting means to insert a single unit in said totalizer when said special key is operated, and means controlled by said totalizer to prevent an incorrect operation of said special key.

35 12. In a calculating machine, the combination of a totalizer, means for indicating the positive resultant of a series of numbers inserted in said totalizer, means for indicating the negative resultant of a set of 40 numbers inserted in said totalizer, number-indicating means to indicate whether said resultant is positive or negative, actuating mechanism adapted to insert a number in said totalizer seriatim, a set of numeral keys 45 adapted to operate said actuating mechanism, means operated by said actuating mechanism to insert a unit in said totalizer whenever said special key is operated, and means controlled by said totalizer to prevent 50 an incorrect operation of said special key.

13. In a calculating machine, the combination of a totalizer, means for inserting a number in said totalizer seriatim, means to shift said number-inserting mechanism and said totalizer relative to each other, a set of 55 number wheels in said totalizer, a set of carrying wheels adapted to operate said set of number wheels, and an additional carrying wheel having no number wheel associated therewith and adapted to be actuated by said number-inserting mechanism and when actuated to operate the number wheel in the lowest decimal place of said totalizer.

14. In a calculating machine, the combination of a totalizer, a set of carrying 60

wheels, a master wheel adapted to insert numbers in said totalizer seriatim, means associated with said carrying wheels to determine the number in said totalizer by the position of said carrying wheels, and an additional carrying wheel in the sub-units decimal place of said totalizer, said carrying wheel being adapted to be operated by said master wheel when said totalizer is in its sub-units decimal place. 75

15. In an algebraic totalizer, the combination of a set of carrying wheels, a master wheel adapted to insert numbers in said totalizer seriatim, a set of digit keys adapted to operate said master wheel differential amounts, a carrying wheel in the sub-units place of said totalizer, and a special key operative on said master wheel and adapted to move said master wheel a single unit whereby said master wheel may insert a single unit into said totalizer by means of the carrying wheel in the sub-units decimal place. 80

16. In a calculating machine, the combination of an algebraic totalizer, a master wheel adapted to insert numbers therein 90 seriatim, a set of carrying wheels in said totalizer adapted to be engaged by said master wheel and said carrying wheels being connected to said number-indicating means, a carrying wheel in the sub-units place of said totalizer, a gear shift to determine the direction in which numbers shall be inserted in said totalizer by said master wheel, and means operative on said master wheel when said master wheel is in engagement with the carrying gear on the sub-units decimal place to advance the master wheel one step in the direction determined by the position of said gear shift. 95

17. In a calculating machine, the combination of an algebraic totalizer, a truck on which said totalizer is mounted, a master wheel adapted to insert numbers in said totalizer seriatim, means to advance said truck step by step in relation to said master wheel, whereby the particular decimal place in which a number is inserted may be determined, and means located in the sub-units place of said totalizer and adapted to be engaged by said master wheel to insert a 100 single unit in said totalizer. 105

18. In a calculating machine, the combination of an algebraic totalizer, a master wheel adapted to insert numbers therein seriatim, a set of digit keys to operate said master wheel a differential amount, and means operated by said master wheel to insert a unit in said totalizer independent of the action of said digit keys. 110

19. In a calculating machine, the combination of a totalizer, a master wheel adapted to insert numbers therein seriatim, a set of digit keys to insert numbers on said master wheel, and means engaged by said master wheel when said master wheel is in the sub- 115 120 125 130

- units decimal place of said totalizer to insert a unit in said totalizer in either direction, and means to prevent the operation of said digit keys when said master wheel is in 5 engagement with said unit-inserting means.
20. In a calculating machine, the combination of an algebraic totalizer, a set of digit keys adapted to insert numbers in said totalizer, means adapted to insert the extra 10 unit in said algebraic totalizer, means concealing the number exhibited by said totalizer when said totalizer passes through zero, and a special key operative on said unit-inserting means to insert a unit in said 15 totalizer and re-exhibit the correct total of the numbers inserted in said totalizer by said digit keys.
21. In a calculating machine, the combination of an algebraic totalizer including 20 number-exhibiting means, means to conceal any exhibited number whenever said totalizer passes through zero, number-inserting means and means operated by said number-inserting means to re-exhibit the correct 25 algebraic total of the numbers inserted in said totalizer.
22. In a calculating machine, the combination of an algebraic totalizer, number-inserting means, means to conceal any exhibited number, said number-concealing 30 means being operated whenever said totalizer passes through zero, and means to insert an additional unit in said totalizer and coincidentally re-exhibit the correct numerical 35 total of the numbers inserted in said totalizer, said unit-inserting means being operated by said number-inserting mechanism.
23. In a calculating machine, the combination of an algebraic totalizer, number-inserting means, a shutter adapted to be operated by said number-inserting means, a second shutter, and means to automatically 40 operate said second shutter when ever said totalizer passes through zero.
45. 24. In a calculating machine, the combination of a totalizer adapted to exhibit two numbers, means to conceal one or the other of said numbers coincident with the passage of said totalizer through zero, a number-inserting 50 mechanism, and means operated by said number-inserting mechanism to conceal one or the other of said numbers.
55. 25. In a calculating machine, the combination of a set of carrying gears, a set of transfer gears, means for exhibiting a total, a shutter device moving coincidently with the highest carrying gear of said set and adapted to conceal said exhibited total, number-inserting mechanism, and a device operated by said number-inserting mechanism also adapted to conceal said total.
60. 26. In a calculating machine, the combination of a set of number wheels adapted to exhibit a positive total, a second set of number wheels adapted to exhibit a negative 65
- total, a shutter device cooperating with said number wheels, mechanism to move said shutter device coincident with the passage of either of said sets of number wheels through zero, number-inserting mechanism, 70 and a shutter device operated by said number-inserting mechanism also cooperating with said number wheels.
27. In a calculating machine, the combination of a totalizer adapted to exhibit 75 either of two numbers, a designating device shiftable to designate either number, number-inserting mechanism, means operated by said number-inserting mechanism to shift said designating device and simultaneously 80 add a predetermined amount to the new number designated, and an automatic concealing device operated coincident with the passage of the totalizer through zero.
28. In a calculating machine, the combination of a totalizer adapted to exhibit 85 either of two numbers, a master mechanism adapted to insert numbers in said totalizer digit by digit in either direction, a designating device shiftable to designate either 90 number, means operated by said master mechanism to shift said designating device and simultaneously add a predetermined amount to the new number designated, and an automatically operated shutter device for 95 concealing the exhibited number coincident with the passage of said totalizer through zero.
29. In a calculating machine the combination of a totalizer embodying digit bearing members, means for actuating said members to register an amount thereon, means to add a digit thereto after an amount has 100 been registered, shiftable means to designate certain digits on said digit bearing members, means operated by said actuating means, and means operative on said digit adding means and said digit designating means whereby a digit may be added to 105 said digit bearing members and the digit designating means simultaneously shifted at will, and a shutter device operated by said digit bearing members.
30. In a calculating machine, the combination of a totalizer adapted to exhibit two 110 numbers, actuating mechanism adapted to insert numbers in said totalizer, a designating device operated by said actuating mechanism and cooperating with each of the numbers, and an automatically operated shutter 115 cooperating with each of said numbers.
31. In a calculating machine, the combination of a totalizer including means to exhibit a total, means to conceal said total when said total is incorrect, number-inserting means to insert numbers in said totalizer, and means operated by said number-inserting means to add an amount to said total and coincidentally exhibit said total.
32. In a calculating machine, the combi- 120

nation of a totalizer including means to exhibit a total, automatic means operating to conceal said total when said total is incorrect, number-inserting means, and means operated by said number-inserting means to add an amount to said total and coincidentally exhibit said total.

33. In a calculating machine, the combination of a totalizer including means to exhibit a total, actuating mechanism adapted to insert numbers therein, means to conceal said total when said total passes through zero as a result of a number inserted by said actuating mechanism, and means operated by said actuating mechanism to add an amount of said total and coincidentally exhibit said total.

34. In a calculating machine, the combination of a totalizer including exhibiting means to exhibit a total, actuating means for said totalizer, means to prevent the exhibition of said total when the same is incorrect, and means operated by said actuating mechanism to add a unit to said total and coincidentally exhibit it.

35. In a calculating machine, the combination of a totalizer adapted to exhibit either a positive or a negative total, number-inserting means, a shutter operated by said number-inserting means cooperating with said exhibited total, an automatically operated shutter also cooperating with said exhibited total.

36. In a calculating machine, the combination of a totalizer having a set of numeral wheels and adapted to exhibit positive and negative totals, number-inserting mechanism, a shutter operated by said number-inserting mechanism cooperating with said exhibited total, and a second shutter controlled by the highest wheel of said totalizer cooperating with said exhibited total.

37. In a calculating machine, the combination of a set of carrying gears, transfer mechanisms connecting said gears, means for exhibiting a total, a shutter device moving coincidentally with the highest carrying gear of said set and adapted to conceal said exhibited total, number-inserting mechanism, and a shutter device also adapted to conceal said total, said shutter device being adapted to be operated by said number-inserting mechanism.

38. In a calculating machine, the combination of an algebraic totalizer, a master wheel, a shutter adapted to be operated by said master wheel, a second shutter, and means to automatically operate said second shutter whenever said totalizer passes through zero.

39. In a calculating machine, the combination of a totalizer adapted to exhibit two numbers, means to conceal one or the other of said numbers coincident with the passage of said totalizer through zero, a master

wheel, and means operated by said master wheel to conceal one or the other of said numbers.

40. In a calculating machine, the combination of a set of carrying gears, a set of transfer gears, means for exhibiting a total, a shutter device moving coincidentally with the highest carrying gear of said set and adapted to conceal said exhibited total, a master wheel, and a device operated by said master wheel also adapted to conceal said total.

41. In a calculating machine, the combination of a set of number wheels adapted to exhibit a positive total, a second set of number wheels adapted to exhibit a negative total, a shutter device cooperating with said number wheels, mechanism to move said shutter device coincident with the passage of either of said sets of number wheels through zero, a master wheel, and a shutter device operated by said master wheel also cooperating with said number wheels.

42. In a calculating machine, the combination of a totalizer adapted to exhibit either of two numbers, a designating device shiftable to designate either number, a master wheel, means operated by said master wheel to shift said designating device and simultaneously add a predetermined amount to the new number designated, and an automatic concealing device operated coincident with the passage of the totalizer through zero.

43. In a calculating machine the combination of a totalizer adapted to exhibit two numbers, a master wheel adapted to insert numbers in said totalizer, a designating device operated by said master wheel and cooperating with each of the numbers, and an automatically operated shutter cooperating with each of said numbers.

44. In a calculating machine, the combination of a totalizer including means to exhibit a total, means to conceal said total when said total is incorrect, a master wheel to insert numbers in said totalizer, and means operated by said master wheel to add an amount to said total and coincidentally exhibit said total.

45. In a calculating machine, the combination of a totalizer including means to exhibit a total, a master wheel adapted to insert numbers therein, means to conceal said total when said total passes through zero as a result of a number inserted by said master wheel, and means operated by said master wheel to add an amount to said total and coincidentally exhibit said total.

46. In a calculating machine, the combination of a totalizer including exhibiting means to exhibit a total, a master wheel for said totalizer, means to prevent the exhibition of said total when the same is incorrect, and means operated by said master wheel to

add a unit to said total and coincidently exhibit it.

47. In a calculating machine, the combination of a totalizer having a set of numeral wheels and adapted to exhibit positive and negative totals, a master wheel, a shutter operated by said master wheel cooperating with said exhibited total, and a second shutter controlled by the highest wheel of said totalizer cooperating with said exhibited total.

48. In a calculating machine, the combination of an algebraic totalizer, actuating mechanism therefor, a set of digit keys directly driving said actuating mechanism, a special key, mechanism operated by said special key to correct the error in said totalizer whenever said totalizer passes through zero, and means controlled by said totalizer to prevent incorrect operation of said special key.

49. In a calculating machine, the combination of an algebraic totalizer, actuating mechanism therefor adapted to insert a number therein seriatim, a set of digit keys operative on said actuating mechanism, a special key, and mechanism operated by said special key to correct the error in said totalizer whenever said totalizer passes through zero, said mechanism preventing an operation of said special key when set to operate the totalizer in the wrong direction.

50. In a calculating machine, the combination of an algebraic totalizer, actuating mechanism therefor, a set of digit keys directly driving said actuating mechanism, a special key, mechanism operated by said special key through said actuating mechanism to correct the error in said totalizer whenever said totalizer passes through zero, and means controlled by said totalizer to prevent an incorrect operation of said special key.

51. In a calculating machine, the combination of an algebraic totalizer, a set of digit keys, means operated by said digit keys, to insert numbers in said totalizer, a special key, means operable by said special key and included in said actuating mechanism to correct the error in said algebraic totalizer whenever the same passes through zero, and an interlock between said digit keys and said special key whereby simultaneous operation of any of said digit keys and said special key is prevented.

52. In a calculating machine, the combination of an algebraic totalizer, a special key, mechanism operated by said special key to correct the error in said totalizer when said totalizer passes through zero, a traveling member, and means controlled by said traveling member to prevent the operation of said special key when said traveling member is in a predetermined position.

53. In a calculating machine, the com-

bination of an algebraic totalizer, a special key, mechanism operated by said special key to correct the error in said totalizer when said totalizer passes through zero, a traveling member, a cam on said traveling member, and means controlled by said cam to prevent the operation of said special key when said cam is in a predetermined position.

54. In a calculating machine, the combination of an algebraic totalizer, a set of digit keys adapted to insert numbers in said totalizer, a special key adapted to correct the error in said totalizer when said totalizer passes through zero, a traveling member, and means controlled by said traveling member determining that the digit keys only may be operated in one predetermined position and the special key only be operated in a second predetermined position.

55. In a calculating machine, the combination of an algebraic totalizer, a set of digit keys adapted to insert numbers in said totalizer, a special key adapted to correct the error in said totalizer when said totalizer passes through zero, a traveling member, a cam on said traveling member, and means controlled by said cam determining that the digit keys only may be operated in one predetermined position and the special key only be operated in a second predetermined position.

56. In a calculating machine, the combination of an algebraic totalizer, actuating mechanism therefor, a set of digit keys, a special key, mechanism operated by said special key to correct the error in said totalizer whenever said totalizer passes through zero, a single key mechanism controlling said digit keys and said special key, and means operative on said single key mechanism to determine whether said digit keys or said special key may be operated.

57. In a calculating machine, the combination of an algebraic totalizer, actuating mechanism therefor adapted to insert numbers in said totalizer seriatim, a set of digit keys, a special key, mechanism operated by said special key to correct the error in said totalizer whenever said totalizer passes through zero, a single key mechanism controlling said digit keys and said special key, and means operative on said single key mechanism to determine whether said digit keys or said special key may be operated.

58. In a calculating machine, the combination of an algebraic totalizer, actuating mechanism therefor, a set of digit keys, a special key mechanism operated by said special key to correct the error in said totalizer whenever said totalizer passes through zero, a single key mechanism controlling the action of said digit keys and said special key, said single key mechanism having its motion determined by stops, and means to shift the relation of said stops with said

- single key mechanism, whereby it may be determined either that said digit keys or said special key may be operated.
59. In a calculating machine, the combination of an algebraic totalizer, actuating mechanism therefor, a set of digit keys, a special key, a set of cams cooperating with said digit key and special key, said cams having their motion determined by movable stops, and means for shifting the relation of said stops to said cams.
60. In a calculating machine, the combination of a traveling carriage, a decimal carriage, means to bring said decimal carriage repeatedly and intermittently into cooperation with said traveling carriage, an algebraic totalizer, actuating mechanism whose action on said totalizer is determined by said decimal carriage, a set of digit keys, a decimal lock to prevent the operation of said digit keys at said pointing-off spaces, and means controlled by said decimal carriage to render said digit keys inoperative on said totalizer at certain predetermined positions on said decimal carriage.
61. In a calculating machine, the combination of a traveling carriage, an algebraic totalizer, means to bring said totalizer repeatedly and intermittently into cooperation with said traveling carriage, actuating mechanism adapted to enter numbers serially into said algebraic totalizer, a decimal lock device adapted to lock said digit keys when said totalizer is in its decimal points or pointing-off spaces, and means whose action is controlled by said traveling carriage to prevent the operation of said digit keys at certain predetermined positions of said traveling carriage.
62. In a calculating machine, the combination of a traveling carriage, an algebraic totalizer adapted to be brought intermittently and repeatedly into cooperation with said traveling carriage, actuating mechanism adapted to enter numbers into said totalizer, a set of digit keys operative on said actuating mechanism, a special key adapted to correct the error in said algebraic totalizer when said totalizer passes through zero, and means controlled by said traveling carriage to determine that said special key shall be locked in certain positions of said traveling carriage, and unlocked in other positions of said traveling carriage.
63. In a calculating machine, the combination of a traveling carriage, an algebraic totalizer, an actuating mechanism, means controlled by said traveling carriage to determine the action of said actuating mechanism on said totalizer, a set of digit keys to control the operation of said actuating mechanism, a decimal lock to render said digit keys inoperative when said totalizer is in its decimal points or pointing-off spaces, and means controlled by said travel-
- ing carriage to prevent the operation of said digit keys at certain predetermined positions thereof.
64. In a calculating machine, the combination of an algebraic totalizer, means to control the computing state of said totalizer, a traveling carriage, actuating mechanism, means controlled by said traveling carriage for repeatedly and intermittently bringing said totalizer into cooperation with said actuating mechanism, a set of digit keys, and a special key adapted to correct the error in said algebraic totalizer when said totalizer passes through zero.
65. In a calculating machine, the combination of an algebraic totalizer, means to control the computing state of said totalizer, a traveling carriage, actuating mechanism, means controlled by said traveling carriage for repeatedly and intermittently bringing said totalizer into cooperation with said actuating mechanism, a set of digit keys, a special key adapted to correct the error in said algebraic totalizer when said totalizer passes through zero, and an interlock between said digit keys and said special key.
66. In a calculating machine, the combination of an algebraic totalizer, means to control the computing state of said totalizer, a traveling carriage, actuating mechanism, means controlled by said traveling carriage for repeatedly and intermittently bringing said totalizer into cooperation with said actuating mechanism, a set of digit keys, a special key adapted to correct the error in said algebraic totalizer when said totalizer passes through zero, and an interlock controlled by said traveling carriage to determine whether one of said digit keys or said special key shall be operated in a predetermined position of said traveling carriage.
67. In a calculating machine, the combination of an algebraic totalizer, means to insert numbers in said totalizer, means to correct the error in said totalizer whenever said totalizer passes through zero, said correcting means being adapted to be operated in either direction according as said totalizer has passed through negative zero or has passed through positive zero, means preventing the operation of said totalizer in the wrong direction by said correcting means, and a restoring lever to release said correcting means in case said means should be partially operated in the wrong direction.
68. In a calculating machine, the combination of an algebraic totalizer, actuating mechanism therefor, means operable in either direction to correct the error of said totalizer when said totalizer passes through zero, means to prevent the operation of said correcting means in a wrong direction, a full stroke mechanism operative on said correcting means, and a restoring lever adapted to release said full stroke mechanism.

69. In a calculating machine, the combination of a set of digit keys, a universal member displaced a constant amount upon the operation of any of said digit keys, a member displaced a differential amount upon the action of any digit keys, a full stroke mechanism effective on said digit keys, and means to release said full stroke mechanism, thereby permitting the key to return to its original position, to release said differential member, thereby allowing it to return to its normal position, and to release said universal member, thereby allowing said universal member to return to its normal position, all of said operations being performed in the order stated.

70. In a calculating machine, the combination of a set of digit keys, a full stroke mechanism operative on said digit keys, a restoring lever to release said full stroke mechanism, and an interlock between said restoring lever and said digit keys, whereby said restoring lever may not be operated unless a digit stands partially depressed.

71. In a calculating machine, the combination of an actuating mechanism, a set of digit keys operative on said actuating mechanism, a full stroke mechanism cooperating with said digit keys, whereby a full stroke of said keys is compelled, a restoring lever adapted to release said full stroke mechanism, and a single key mechanism operative on said digit keys and said restoring lever.

72. In a calculating machine, the combination of an actuating mechanism, a set of digit keys operative on said actuating mechanism, a full stroke mechanism cooperating with said digit keys, whereby a full stroke of said keys is compelled, a restoring lever adapted to release said full stroke mechanism, and a single key mechanism preventing the operation of said restoring lever unless one of said keys stands partially depressed.

73. In a calculating machine, the combination of an algebraic totalizer, actuating mechanism therefor, a set of digit keys, mechanism to correct the error in said totalizer whenever said totalizer passes through zero, a single key mechanism controlling said digit keys and said totalizer correcting means, and means operative on said single key mechanism to determine whether said digit keys or said totalizer correcting mechanism may be operated.

74. In a calculating machine, the combination of an algebraic totalizer, a traveling carriage, actuating mechanism, means controlled by said traveling carriage for repeatedly and intermittently bringing said totalizer into cooperation with said actuating mechanism and special key, means to correct the error in said algebraic totalizer when said totalizer passes through zero, and

an interlock between said digit keys and said correcting means.

75. In a calculating machine, the combination of a moving carriage, calculating mechanism, means to determine whether said calculating mechanism shall operate in addition or in subtraction, a bar moving with said carriage, said bar being supported so as to have freedom of motion at a direction at right angles to said carriage but to be constrained to move with said carriage, and a set of cams mounted on said bar to control the action of said calculation determining means.

76. In a calculating machine, the combination of a traveling carriage, a decimal carriage, means to bring said decimal carriage repeatedly and intermittently into cooperation with said traveling carriage, a totalizer, means to determine whether said totalizer shall calculate in addition or in subtraction, a floating bar moving with said carriage and carrying a set of cams to determine the position of said calculating determining means, and means connecting said bar with said carriage, whereby said bar is allowed freedom of motion at right angles to the line of motion of said carriage, but is constrained to advance synchronously with said carriage.

77. In a calculating machine, the combination of computing mechanism, a set of digit keys, calculating determining means to determine whether said digit keys shall operate said computing mechanism in addition or in subtraction, a traveling member, a cam moving synchronously with said traveling member, a bar on which said cam is mounted, a bearing for said bar situated in alignment with the point of action of said cam on said calculating determining means, and connections between said bar and said traveling carriage whereby said bar is permitted freedom of motion in respect to said traveling carriage except at the point of action between said cam and said calculating determining means.

78. In a calculating machine, the combination of a moving carriage, a bar traveling with said carriage, said bar having an approximately V section, a single bearing for said bar mounted on the framework of the machine, and loose connections between said bar and said carriage whereby said bar has freedom of motion respecting said carriage, except at the point of engagement with said single bearing.

79. In a calculating machine, the combination of a moving carriage, a bar traveling with said carriage, said bar having an approximately V section, an adjustable bearing for said bar mounted on the framework of the machine, and loose connections between said bar and said carriage whereby said bar has freedom of motion respecting

said carriage, except at the point of engagement with said single bearing.

80. In a calculating machine, the combination of calculating mechanism, and means to determine whether said calculating mechanism shall operate in addition or subtraction, said means including a floating bar carrying a set of cams and supported by a single bearing located above the point of 10 action of said cams.

81. In a calculating machine, the combination of calculating mechanism, means to determine whether said calculating mechanism shall operate in addition or subtraction, a set of cams to operate on said calculating determining means, a moving member, a floating bar moving synchronously with said member and on which said cam is supported, and a single bearing for 15 said bar mounted on the framework of the machine, said bearing being located vertically above the point of action of said cams on said calculating determining means.

82. In a calculating machine, the combination of a moving carriage, calculating mechanism, means to determine whether said calculating mechanism shall operate in addition or in subtraction, a floating bar loosely connected to said traveling member, 20 and a single bearing for said bar mounted on the framework of the machine, said bearing consisting of a pair of independent rollers which contact with a pair of oppositely pointed V-shaped longitudinal ridges in said 25 bearing, whereby said bar is constrained at the point of contact with said bearing, but is free to move at other points.

83. In a calculating machine, the combination of a totalizer including a totalizer 30 framing, a traveling member, a cam located on said traveling member to determine whether said calculating machine shall be operated in addition or subtraction according to the position of said traveling member, a support for said cam including a skeleton 35 frame, and a floating bar moving with said traveling member and having locating notches thereon to determine the position of said frame.

84. In a calculating machine, the combination of a totalizer, a traveling member, an adjustable cam located on said traveling member to determine whether said calculating machine shall be operated in addition or subtraction according to the position of said traveling member, a support for said cam including a skeleton frame, and a floating bar moving with said traveling member and having locating notches thereon to determine the position of said frame.

85. In a calculating machine, the combination of a cam supporting structure consisting of a pair of side plates, tie bars locating said plates in a definite position 55 with respect to each other, a cam supported

between said side plates, said cam being removable, calculating determining means to determine whether said calculating machine shall operate in addition or subtraction, said calculating determining means being positioned to contact and be operated by said cam, a plurality of surfaces on said cam, and means of attaching said cam to said supporting frames, the surfaces on said cam being so proportioned that when said cam is in one position the calculating determining means will be positioned to determine addition, and when said cam is turned end for end the calculating determining means will be positioned to determine subtraction. 75

86. In a calculating machine, the combination of a cam supporting structure consisting of a pair of side plates, tie bars locating said plates in a definite position with respect to each other, a cam supported between said side plates, said cam being removable, calculating determining means to determine whether said calculating machine shall operate in addition or subtraction, said calculating determining means being positioned to contact with and be operated by said cam, a plurality of surfaces on said cam, means of attaching said cam to said supporting frames, the surfaces on said cam being so proportioned that when said cam is in one position the calculating determining means will be positioned to determine addition, and when said cam is turned end for end the calculating determining means will be positioned to determine subtraction, and when said cam is turned up side down the calculating determining means will be positioned to 80 determine non-operation of the machine. 90

87. In a calculating machine, an adjustable cam for determining the operations to be performed by the machine, said cam being formed of a block having a fin projecting from one side and a plane surface on the other side whereby said block may be turned end for end to change the kind of calculation 105 performed by the machine. 110

88. In a calculating machine, the combination of a gear shift including a pair of complementary levers, a traveling member, a cam mounted on said traveling member, said cam being adapted to contact with said levers and having a fin on one edge to contact with one lever, and a surface to contact with the complementary position of the other lever, said cam being also provided with removable attaching devices to said traveling member whereby said cam may be turned end for end and thus change the cam determined position of the complementary levers. 115 120

89. In a calculating machine, the combination of a pair of complementary levers, a cam having complementary surfaces thereon adapted to contact with said complementary levers, a traveling member supporting said 130

cam, and cam attaching means for holding said cam to said traveling member, said means permitting the locating of said cam in either of two positions in the second of which the position of the cam determined position of the complementary levers is reversed.

90. In a calculating machine, the combination of a pair of complementary levers, a traveling member, and an adjustable cam mounted on said traveling member, said cam when located in one position determining a certain position of the complementary levers, when turned end for end determining the reverse position of the complementary levers, and when turned upside down determining a third position of the complementary levers.

91. In a calculating machine, the combination of a jumping totalizer, a set of digit keys, a gear shift to determine the operation of said digit keys on said totalizer, a set of cams to operate said gear shift, a floating bar, and a supporting structure having a mounting for said cam and also a pick-up lug for said jumping totalizer, said cam supporting structure being movable along said floating bar and being located by locating notches cut in said bar whereby the adjustment of said frame along said bar will simultaneously determine the zone of calculation of said jumping totalizer and the kind of calculation to be performed in said zone.

92. In a calculating machine, the combination of an algebraic totalizer, a set of digit keys, a gear shift to determine the operation of said digit keys on said totalizer, a set of cams to operate said gear shift, a floating bar, and a supporting structure having a mounting for said cam and also a pick-up lug for said jumping totalizer, said cam supporting structure being movable along said floating bar and being located by locating notches cut in said bar whereby the adjustment of said frame along said bar will simultaneously determine the zone of calculation of said jumping totalizer and the kind of calculation to be performed in said zone.

93. In a calculating machine, the combination of a calculating mechanism, calculating determining means, a traveling member to operate on said calculating determining means when said traveling member has reached a predetermined position, a cam, a cam bar traveling with said traveling member and on which said cam is mounted, and a mounting for said cam consisting of a pair of side plates, tie bars uniting said plates, a locating notch to cooperate with locating notches in said bar, a lug to determine the points of operation of said calculating mechanism, and a spring latch to hold said supporting frame in its located position on said bar.

94. In a calculating machine, the combina-

tion of calculating determining means, a cam to operate said means, a supporting framework for said cam, said cam consisting of a block having a plane surface on one side and an L-shaped surface on the other side and being capable of attachment to said side plates, either with its L-shaped surface uppermost or with its plane surface uppermost, whereby the same block serves when placed in different positions with respect to said side plates to determine different conditions of the calculating mechanism.

95. In a calculating machine, the combination with a gear shift, a floating cam having two points at which it is controlled and which by its position controls said gear shift, and means for controlling one of said points of said floating cam, of means for controlling the other of said points comprising a plate movably mounted on the framework and having a cam surface which controls said other point, and a lever to control the position of said plate.

96. In a calculating machine, the combination with a gear shift, a floating cam having two points at which it is controlled and which by its position controls said gear shift, of a plate pivoted to the framework of the machine and having a cam surface acting on one of said points of control to determine in one position of said cam plate one position of said floating cam, and in a second position of said cam plate determining a second position of said floating cam, and when in a third position being ineffective on said floating cam; and a second means for controlling said floating cam when said cam plate is in its said third position.

97. In a calculating machine, the combination with a gear shift, a floating cam having two points at which it is controlled and which by its position controls said gear shift, of a plate pivoted to the framework of the machine and having a cam surface acting on one of said points of control to determine in one position of said cam plate one position of said floating cam, and in a second position of said cam plate determining a second position of said floating cam, and when in a third position being ineffective on said floating cam; a second means for controlling said floating cam when said cam plate is in its said third position; and a manually operated lever to control the positions of said cam plate.

98. In a calculating machine, a gear shift device, a cam controlling the position of said gear shift device, and a pair of swinging plates controlling the position of said cam, each of said plates having three positions, in two of which positions the control of the first plate is effective on said cam and the control of the second plate ineffective and in the third position the control of the sec-

ond plate is effective upon said cam and the control of the first plate ineffective.

99. In a calculating machine, a gear shift device, a cam controlling the position of said gear shift device, a pair of swinging plates controlling the position of said cam, each of said plates having three positions, in two of which positions the control of the first plate is effective on said cam and the control of the second plate ineffective and in the third position the control of the second plate is effective upon said cam and the control of the first plate ineffective, and means for shifting said first and second plates simultaneously.

100. In a calculating machine, a gear shift device, a cam controlling the position of said gear shift device, a pair of swinging plates controlling the position of said cam, each of said plates having three positions, in two of which positions the control of the first plate is effective on said cam and the control of the second plate ineffective and in the third position the control of the second plate is effective upon said cam and the control of the first plate ineffective, a manually operated lever for shifting the first and second plates simultaneously.

101. In a calculating machine, a gear shift device, a cam controlling the position of said gear shift device, a pair of swinging plates controlling the position of said cam, each of said plates having three positions, in two of which positions the control of the first plate is effective on said cam and the control of the second plate ineffective and in the third position the control of the second plate is effective upon said cam and the control of the first plate ineffective, a manually operable lever for shifting the said first and second plates simultaneously, and means to hold said lever in any of its three positions.

102. In a calculating machine, a gear shift device, a floating cam controlling the position of said gear shift device, a pair of swinging plates controlling the position of said cam, each of said plates having three positions, in two of which positions the control of the first plate is effective on said cam and the control of the second plate ineffective and in the third position the control of the second plate is effective upon said cam and the control of the first plate ineffective, and a manually operable lever for shifting the said first and second plates simultaneously, and means to hold said lever in any of its three positions.

103. In a calculating machine, a gear shift device, a floating cam controlling the position of said gear shift device, and a pair of swinging plates controlling the position of said cam, each of said plates having three positions, in two of which positions the control of the first plate is effective on said cam and the control of the second plate in-

effective and in the third position the control of the second plate is effective upon said cam and the control of the first plate ineffective.

104. In a calculating machine, a gear shift device, a floating cam controlling the position of said gear shift device, a pair of swinging plates controlling the position of said cam, each of said plates having three positions, in two of which positions the control of the first plate is effective on said cam and the control of the second plate ineffective and in the third position the control of the second plate is effective upon said cam and the control of the first plate ineffective, and means for shifting said first and second plates simultaneously.

105. In a calculating machine, the combination with a gear shift device, a cam controlling the position of said gear shift device, a plate pivotally mounted on the framework of the machine and having a cam surface acting to position the first mentioned cam, a lever pivoted upon said frame, a second cam plate pivoted upon said lever and having a cam surface adapted when said plate is swung about its pivot to act on the said first mentioned cam, said second cam plate being adapted when in one of its positions to control said first mentioned cam by the swinging of said lever, and means for shifting both said cam plates simultaneously, one about its pivot on the framework and the other about its pivot on said lever.

106. In a calculating machine, a gear shift device, a floating cam controlling the position of said gear shift device, a pair of swinging plates controlling the position of said cam, each of said plates having three positions, in two of which positions the control of the first plate is effective on said cam and the control of the second plate ineffective and in the third position the control of the second plate is effective upon said cam and the control of the first plate ineffective, and a manually operable lever for shifting the said first and second plates simultaneously, and means to hold said lever in any of its three positions.

107. In a calculating machine, the combination of a gear shift device, a cam controlling the position of said gear shift device, a cam plate pivotally mounted on the framework of the machine for controlling the position of said cam, a lever pivoted upon said frame, a second cam plate pivoted upon said lever, said second cam plate being adapted to also control said cam when in certain positions, and means for shifting said cam plates simultaneously.

108. In a calculating machine, the combination of a gear shift device, a cam to control said gear shift device, a cam plate pivotally mounted upon the frame and

- adapted to control said cam when in certain positions, a manually operable lever connected to said cam plate and controlling said position, a traveling member, calculation determining cams mounted on said traveling member, a lever pivoted on the framework and adapted to be operated by said calculation controlling cams, and a second cam plate operative on said cam and pivoted on 10 said lever.
109. In a calculating machine, the combination of a gear shift device, a cam to control said gear shift device, a cam plate pivotally mounted upon the frame and 15 adapted to control said cam when in certain positions, a manually operable lever connected to said cam plate and controlling said position, a traveling member, calculation determining cams mounted on said 20 traveling member, a lever pivoted on the framework and adapted to be operated by said calculation controlling cams, a second cam plate operative on said cam and pivoted on said lever, and means for shifting said 25 second cam plate simultaneously with the shifting of said first cam plate.
110. In a calculating machine, the combination of a gear shift device, a cam pivoted on the framework and adapted to control 30 the position of said gear shift device, a lever pivoted on the framework, a cam plate pivoted on said lever and also adapted to control the position of said gear shift device and traveling member, means mounted 35 on said traveling member to control the position of said lever, a manually operable lever to control the position of said first cam plate, and means connecting said cam plates whereby the operation of said lever and resulting shifting of the first cam plate will 40 also shift the second cam plate.
111. In a calculating machine, the combination of a gear shift device, a floating cam controlling the position of said gear 45 shift device, a pair of cam plates, one of which is pivoted on the framework and the other of which is pivoted on a lever, said cam plates cooperating with each other to control the position of one point in said 50 floating cam, and a manually operable lever controlling the position of a second point in said floating cam.
112. In a calculating machine, the combination of a traveling member, calculation 55 determining cams on said traveling member, a pair of levers, a linkage to cause said levers to move complementary amounts, whereby the position of said levers may be determined by said cams, a cam plate pivoted 60 on one of said levers, a gear shift device, a floating cam controlling the position of said gear shift device, and means to control said floating cam from said cam plate.
113. In a calculating machine, the combination of a gear shift device, a floating 65 cam controlling the position of said gear shift device, a pair of cam plates having complementary slots cut therein controlling the position of one point of said floating cam, and a lever controlling a second point 70 in said floating cam.
114. In a calculating machine, the combination of a traveling member, a pair of levers, a linkage connecting said levers to cause them to move complementary 75 amounts, and a cam mounted on said traveling member, said cam being shaped that when in one position it determines that said levers shall take one position and when turned end for end determines that said 80 lever shall take the complementary position.
115. In a calculating machine, the combination of a pair of swinging cam plates, the first of said cam plates having a slot 85 therein narrow at each end and wide at the middle, a second of said cam plates having a slot therein which is narrow in the middle and wide at each end, and means connecting said cam plates for shifting them simultaneously. 90
116. In a calculating machine, the combination of a pair of swinging cam plates, the first of said cam plates having a slot 95 therein narrow at each end and wide at the middle, a second of said cam plates having a slot therein which is narrow in the middle and wide at each end, means connecting said cam plates for shifting them simultaneously, and a lever adapted to be acted on by either 100 of said cam plates.
117. In a calculating machine, the combination of a pair of swinging cam plates, the first of said cam plates having a slot 105 therein narrow at each end and wide at the middle, a second of said cam plates having a slot therein which is narrow in the middle and wide at each end, means connecting said cam plates for shifting them simultaneously, a floating lever, and a connection between 110 said floating lever and said cam plates whereby when said cam plates are in their extreme positions said floating lever is controlled by the first cam plate without interference from the second and when said cam plates are in an intermediate position said floating lever is controlled by said second cam plate without interference from the first. 115
118. In a calculating machine, the combination of an algebraic totalizer adapted to exhibit the true resultant of a sum of positive and negative quantities, a set of digit keys, an actuating mechanism operative by said keys, a gear shift device controlling 120 the action of said actuating mechanism upon said totalizer, a universal correcting lever which when operated will reverse the action of said actuating mechanism on said totalizer, printing mechanism, a color shift de- 125 130

vice to alter the appearance of the work done by said printing mechanism, and a connection between said universal correcting lever and said color shift device whereby the throwing of said lever into its alternative position simultaneously throws the color shift device into its alternative position.

119. In a calculating machine, the combination of a moving carriage, a decimal carriage, means to return said decimal carriage to a normal position, a set of lugs on said traveling carriage, a pair of latches on said decimal carriage, said latches being adapted to contact with any of said lugs, one of said latches engaging the front portion thereof and the other of said latches engaging the rear portion thereof.

120. In a calculating machine, the combination of a decimal carriage, means to restore said decimal carriage to a normal position, a latch on said decimal carriage, a traveling member having a series of connecting lugs thereon, means to hold said latch in a position to be engaged by any of said lugs when said decimal carriage is in a normal position, a second latch mounted on said decimal carriage, said second latch being held out of the path of said lugs when said decimal carriage is held in a normal position, and means to move said second latch into engagement with said lugs coincident with the removal of said decimal carriage from its normal position.

121. In a calculating machine, the combination of a totalizer slidably mounted in the framework, means to hold said totalizer in a normal position, a latch moving with said totalizer, a traveling carriage, a lug on said traveling carriage adapted to engage said latch when said totalizer is in its normal position, a second latch moving with said totalizer, said second latch being held out of the path of said lugs when said totalizer is in its normal position, and means to move said second latch into the path of said lugs coincident with the movement of said totalizer from its normal position.

122. In a calculating machine, the combination of a decimal carriage slidably mounted in the framework, means to return said decimal carriage to a normal position, a stop determining the normal position of said decimal carriage, an adjustable abutment on said decimal carriage adapted to contact with said stop, a latch on said decimal carriage, and means connecting said abutment with said latch whereby said latch is moved to its alternative position upon the contact of said abutment and said stop.

123. In a calculating machine, the combination of a reciprocating decimal carriage, a stop determining the normal position of said decimal carriage, an abutment on said decimal carriage, said abutment being slid-

ably mounted with respect to said carriage, and a latch on said carriage whose position is controlled by said slidable abutment.

124. In a calculating machine, the combination of a reciprocating decimal carriage, means to hold said carriage in a normal position, a stop determining the normal position of said carriage, an abutment on said decimal carriage adapted to contact with said stop and thereby determining the normal position of said decimal carriage, a member adjustable with respect to said decimal carriage on which said abutment is slidably mounted, a latch on said decimal carriage whereby the position of the former determines the position of the latter.

125. In a calculating machine, the combination of a reciprocating decimal carriage, means to determine the normal position of said decimal carriage, said means including an abutment adjustable with respect to said decimal carriage, but movable when in any of its adjusted positions, a latch in said decimal carriage, and means to control said latch from said adjustable abutment, said control being effective independent of the adjusted position of said abutment.

126. In a calculating machine, the combination of a decimal carriage, means to hold said decimal carriage in its normal position, an adjustable rack on said decimal carriage, an abutment movable with respect to said rack, a latch on said decimal carriage, and a lever connecting said movable abutment with said latch.

127. In a calculating machine, the combination of a decimal carriage, means to hold said decimal carriage in a normal position, an adjustable rack on said decimal carriage, an abutment slidably mounted with respect to said rack, said abutment having its upper surface plane, a lever contacting with said plane surface, and a latch mounted on said decimal carriage and controlled by said lever.

128. In a calculating machine, the combination of a decimal carriage, means to determine a normal position of said decimal carriage, said means including a stop fixed on the frame-work and a slidable abutment, a set of digit keys, an interlock between said keys and said decimal carriage to lock said keys when said decimal carriage is in certain positions, and a control for said interlock interposed between said stop and said abutment.

129. In a calculating machine, the combination of calculating mechanism, a traveling member, a decimal carriage adapted to be connected intermittently to said traveling member, a set of digit keys, a bar moving with said traveling member, said bar serving as a support for a set of cams, and an interlock for said decimal carriage, said interlock being controlled jointly by said decimal car-

riage and any of said cams whereby the operation or non-operation of said digit keys is controlled by the joint action of said traveling member and said jumping decimal carriage.

130. In a typewriter calculating machine, the combination with a traveling typewriter carriage, of a jumping decimal carriage adapted to be connected to said traveling carriage repeatedly and intermittently, a bar rigidly attached to said typewriter carriage and traveling therewith, a set of digit keys, a lock for said jumping carriage, a lock for said traveling bar, and connections between said digit keys and said locks whereby the operation of any of said digit keys will lock both carriages.

131. In a calculating machine, the combination of a jumping decimal carriage, a traveling carriage, a bar rigidly mounted on said traveling carriage and traveling therewith, means to connect said jumping carriage to said traveling carriage repeatedly and intermittently, a lock for said decimal carriage, a second lock operative on said traveling bar, a set of digit keys, and means connecting said digit keys and said locks to lock both said bar and said decimal carriage on the down stroke of any of said keys, and to release said locks when the operated digit key has completed its down stroke.

132. In a calculating machine, the combination of a jumping decimal carriage, a traveling carriage adapted to pick up said decimal carriage at certain predetermined intervals, a rack on said decimal carriage, a lock cooperating with said rack, a rack rigidly mounted on said traveling carriage, a second lock cooperating with said rack, a digit key, and means connecting said digit key to both of said locks to operate said locks simultaneously upon the operation of said digit key.

133. In a calculating machine, the combination of a jumping decimal carriage, a traveling carriage adapted to pick up said decimal carriage at certain predetermined intervals, a rack on said decimal carriage, a lock cooperating with said rack, a rack on said traveling carriage, a second lock cooperating with said rack, a digit key, and means to connect said digit key with both of said locks to operate said locks upon the initiation of the downstroke of said key and to release them upon the completion of said downstroke.

134. In a calculating machine, the combination of a jumping decimal carriage, a totalizer mounted on said decimal carriage, said totalizer having a locked gear chain, means to insert numbers in said totalizer seriatim, a traveling carriage, a floating bar on said traveling carriage, means to re-

peatedly and intermittently connect said decimal carriage to said floating bar, a carriage lock for said decimal carriage, a second bar mounted on said traveling carriage, a carriage lock cooperating with said second bar, means to unlock the totalizer gear chain at the actuated point, a digit key, and means connecting said digit key with the three previously recited locks to unlock said totalizer gears and operate both of said carriage locks on the operation of said digit key.

135. In a calculating machine, the combination of an algebraic totalizer, means to actuate said totalizer, means to correct the error in said totalizer when said totalizer passes through zero, and an automatically exhibited instruction device whereby the operator is informed at what time and in what direction to operate said totalizer correcting means.

136. In a calculating machine, the combination of an algebraic totalizer, a set of digit keys to insert numbers therein, a special key to correct the error in said totalizer when said totalizer passes through zero, and an automatically exhibited instruction device to inform the operator at what times and in what direction to operate said correcting key.

137. In a calculating machine, the combination of an algebraic totalizer, means to insert a number therein seriatim, a set of digit keys to operate said number-inserting means, means to correct the error in said totalizer when said totalizer passes through zero, and an automatically exhibited instruction device informing the operator in what direction and at what time to operate said totalizer correcting means.

138. In a calculating machine, the combination of an algebraic totalizer, means to insert a number therein seriatim, a set of digit keys operative on said number-inserting means, means to correct the error in said totalizer when said totalizer passes through zero, and an automatically exhibited instruction device informing the operator in what direction to correct the totalizer, whereby the operator is informed whether said totalizer is to be corrected in addition or in subtraction.

139. In a calculating machine, the combination of a reciprocating decimal carriage, an abutment on said decimal carriage, said abutment being slidably mounted with respect to said carriage, and a latch on said carriage, whose position is controlled by said abutment.

140. In a calculating machine, the combination of an algebraic totalizer, means to actuate said totalizer, means to correct the error in said totalizer when said totalizer passes through zero, and an automatically

exhibited instruction device to inform the operator at what time a correcting operation is required.

141. In a calculating machine, the combination of an algebraic totalizer, a set of digit keys to insert numbers therein, means to correct the error in said totalizer when said totalizer passes through zero, a special key to operate said correcting means, and an automatically exhibited instruction device to inform the operator at what time to operate said special key.

142. In a calculating machine, the combination of an algebraic totalizer, means to insert a number therein seriatim, a set of digit keys to operate on said number-inserting means, means to correct the error in said totalizer when said totalizer passes through zero, and an automatically exhibited instruction device informing the operator when it is necessary to operate said totalizer-correcting means.

143. In a calculating machine, the combination of a totalizer, a set of numeral keys, actuating mechanism directly driven by the operation of said numeral keys, said actuating mechanism being adapted to insert numbers in said totalizer either positively or negatively, means located in said totalizer adapted to exhibit two sets of numbers, one set of numbers being adapted to exhibit positive totals and the other set being adapted to exhibit negative totals, means for concealing one or the other of said sets of numbers, and means operated by said number inserting mechanism and brought into action subsequent to the insertion of a number to insert an additional unit in said totalizer under certain circumstances, whereby the correct resultant of a series of positive and negative numbers may be exhibited.

144. In a calculating machine, the combination of a totalizer, a master wheel to insert numbers in said totalizer, a set of keys adapted to drive said master wheel, means to determine the direction in which said keys will drive said master wheel, thereby making it possible to insert a number into said totalizer either positively or negatively, means to indicate when said totalizer has passed through zero, and means operative on said master wheel and brought into action after the insertion of a number to insert an additional unit in said totalizer, said unit inserting means being adapted to drive said master wheel but being independent of the action of any of said numeral keys.

145. The combination with the number-keys of a computing machine, of a series of locking elements, means for causing said elements to lock all of said keys, and other

means for causing said elements to lock all but one of said keys, while permitting the remaining key to be operated.

146. The combination with the number-keys of a computing machine, of a series of key-locking elements, means for moving and holding said elements in certain relative positions, such as to prevent the operation of any of said keys, and means for moving and holding certain of said elements in different relative positions, such as to prevent the operation of all but a selected one of said keys, which is left free to be operated.

147. The combination with the number-keys of a computing machine, of a series of locking elements, means for causing said elements to lock all of said keys, and other means for causing said elements to lock certain only of said keys, any key not so locked being free to be operated.

148. The combination with the number-keys of a computing machine, of a series of key-locking elements, means for moving and holding said elements in certain relative positions, such as to prevent the operation of any of said keys, and means for moving and holding certain of said elements in different relative positions, such as to prevent the operation of certain only of said keys, any key not so locked being free to be operated.

149. In a calculating machine, the combination of a series of numeral keys, a special key, devices actuated by said keys, a series of single-key cams permitting the operation of but one numeral key at a time and including a special pair of cams which together control said special key, and means for spreading said special cams apart to permit the operation of said special key and to prevent the operation of said numeral keys, and for drawing said special cams together to lock said special key and to permit the operation of a numeral key.

150. In a calculating machine, the combination of a series of numeral keys, a special key, devices actuated by said keys, a series of single-key cams permitting the operation of but one numeral key at a time and including a special pair of cams which together control said special key, means for spreading said special cams apart to permit the operation of said special key and to prevent the operation of said numeral keys and for drawing said special cams together to lock said special key and to permit the operation of a numeral key, and a traveling carriage controlling said means.

In witness whereof I have hereunto subscribed my name.

ARTHUR F. POOLE.
